ABSTRACT: A sample, or printed form, applicator machine for affixing printed forms, or samples of a wide variety of products, to brochures, signatures, envelopes or other carrier

sheets, wherein a carrier sheet feeder feeds individual carrier sheets in timed relationship onto a conveyor, which positions them and carries them through the machine. Above the carrier sheet conveyor is a sample (or printed form) feeding mechanism which feeds individual samples (or printed forms) to a sample conveyor in timed relationship to the feeding of carrier sheets, and including means whereby each sample (or printed form) is positioned in a predetermined manner with respect to the carrier sheet to which it is to be affixed; and then as the sample (or printed form) is carried toward the carrier sheet by a sample transfer mechanism, a glue-applying mechanism is actuated to apply a predetermined amount of glue to the underside of the sample (or printed form) at a predetermined position on the sample or to the top of the carrier sheet at a predetermined position on the carrier sheet. The sample transfer mechanism affixed the sample to the carrier sheet at a predetermined position on the carrier and the carrier then progresses onward to a delivery means, or alternatively through another apparatus such as a folder, and/or slitter, which performs additional operations upon the sample carrying carrier sheet. A number of interdependent detection systems are employed whereby the failure of any element of the machine to perform its intended function properly is detected and appropriately compensated for prior to subsequent operational steps; so that either samples or carrier sheets which are improperly fed, or for which no counterpart has been properly fed, are automatically removed from the machine in reusable form, without the application of glue, without stopping the operation of the machine, and in such a manner as to greatly reduce the likelihood of the apparatus jamming up or malfunctioning. The operation of the apparatus is cyclic and is capable of automatically delivering carrier sheets with samples (or printed forms) affixed thereto, and thereafter folded one or more times if desired, at a rate of many thousands per hour.

AUTOMATIC TIPPING MACHINE

BACKGROUND OF THE INVENTION

The apparatus of this invention has to do with the placement and affixing of samples of a myriad of products, which may take such forms as packets containing samples of perfumes, cosmetics, food products, etc., strips of paper carrying sample fabric swatches adhered thereto, paper strips coated with microencapsulated fragrances, razor blades, sticks of gum, printed materials, etc., each of which is affixed to a carrier sheet. The term "sample" as used herein is intended to refer to any article which is affixed to a carrier sheet. The carrier sheets may take the form of a brochure, a signature, a paper sheet, a cardboard sheet, an envelope, or any other type of carrier which may be used as, or as a part of, an advertising medium. The carrier sheet generally carries a printed message describing and promoting the product to which a sample is attached, and often a portion of the carrier sheet constitutes an order blank which may be used by a recipient to order an additional quantity of the product. In some cases a printed form, instead of an actual sample, is attached to a carrier sheet and may take the form of a coupon, a reply card, an order form, etc. Often the apparatus is directed to the affixing of samples or printed forms onto envelopes or the like which may be readily transmitted to prospective customers by mail or otherwise.

More specifically, the apparatus of this invention is directed to an automatic machine for affixing packets, containing samples of cosmetics, detergents, or other commodities which a manufacturer or a distributor wishes the purchasing public to try, to a mailer or to a remittance envelope furnished by a department store for the use of the customer and enclosed with his monthly bill. The apparatus achieves all of the foregoing with a minimum of human labor and with an efficiency and speed which has been heretofore unattainable.

Ordinarily, manufacturers and distributors of products rely extensively on printed advertising material to communicate with and advise the purchasing public of the attributes of a particular commodity. It has been found that providing a detachable order blank that is easy to fill out makes such printed advertising material more effective in producing sales. It has also been found that potential customers are more highly motivated to purchase when a trial sample of a new product, or a sample of an existing product with which they may be unfamiliar, is made available. A potential customer is more likely to purchase a new product, or a product with which he is not familiar, if he is able to try it first.

Test mailings have demonstrated that when descriptive promotional material, preferably with a detachable order form included, is put in the hands of prospective purchasers, with a sample of the product affixed thereto, the percentage of such prospective purchasers who actually buy the product is very greatly increased. In cases where it is impractical to affix an actual sample of a product, a coupon is often affixed instead offering a sample of the product—either free or at a reduced price.

High-speed automatic equipment is available for producing such printed promotional materials in large volume and at low cost, and for producing a wide range of product samples, either in packets, in individual small packages, in paperback swatches, etc. However, as far as is known, the prior art has not disclosed fully automated apparatus by means of which a wide variety of types and sizes of individual samples may be affixed to an equally wide variety of individual carriers, with the capability of predetermining the position of the sample on the carrier, and capable of thereafter making one or more folds in the carrier, or, alternately, of delivering the carrier unfolded with the sample affixed thereto.

For the most part, such operations have involved time consuming and costly manual labor. In other words, if one should desire individual samples attached to a mailing card or envelope, scores of women would manually affix the samples, at the desired place on the carrier, in a very time-consuming

operation. Firstly, a sample would have to be manually picked up, glue applied to one side of the sample and the sample then affixed in the appropriate spot on the mailer. Once the samples were affixed, the carrier sheets, with the samples attached, did not lend themselves to stacking in, and being separated by, the feeder of a folding machine, so that if the carriers were then to be folded, this would also be done as a hand operation. In some cases the carrier sheets have first been folded automatically in a folding machine, and the women who affix the samples then unfold, or open, each sheet, affix the sample, and then refold the carrier sheet—all as a manual operation. It can readily be seen that an advertising campaign or promotion involving literally millions of mailers would be totally out of the question under these circumstances because of the prohibitive amount of time required to complete the operation, as well as the high cost involved. The apparatus of the herein disclosed invention is intended to automatically produce mailers with samples affixed, and folded as required, at the rate of many thousands per hour. The savings in labor and overall costs are manifest. An even more important result is the ability to complete such operations within the time limits available to meet the mailer's deadline requirements.

It is, therefore, an object of this invention to provide an apparatus for affixing samples to sample carriers.

It is a further object of this invention to provide an efficient high-production machine for applying samples to carriers automatically.

It is a further object of this invention to provide a fully automated apparatus for affixing samples of a wide variety of different materials to a wide variety of types of carriers, the resultant of which can thereby be prepared in the shortest possible time for mass distribution to the purchasing public and at a minimum of cost.

It is still another object of this invention to provide an apparatus for automatically feeding a carrier, such as an envelope or mailing piece, affixing a product sample or printed form to the carrier and thereafter folding the carrier once, or more than once, which may then be distributed through the United States mails or otherwise.

These and other further, important objectives of the invention will become more apparent when taken in conjunction with the following commentary and drawings wherein like numerals of reference indicate like elements throughout the several views and wherein:

FIG. 1 is a side view of the sample affixing machine of this invention in somewhat schematic form;

FIG. 2 is a more detailed view of the sample separating, conveying, transferring and applying means of the apparatus depicted in FIG. 1;

FIG. 2A is a view taken along the line 2A—2A of FIG. 2;

FIG. 2B is a diagrammatic side elevational view of alternate sample registration means;

FIG. 3 is a plan view along the line 3—3 of FIG. 2 showing the means for mounting the photocell and light for detecting the presence or absence of a sample on the sample transfer wheel;

FIG. 4 is a more detailed view of the sample transferring and applying members depicted in FIG. 2;

FIG. 5 is a plan view, partly in section, of the sample transferring and applying members depicted in FIG. 4;

FIG. 14 is a front elevational view of the shuttle and gate depicted in FIGS. 12 and 13;

FIG. 15 is a schematic circuit diagram showing the electromechanical means used for sensing for and reacting to the presence or absence of a carrier sheet or a sample at the appropriate positions in the apparatus as depicted in FIGS. 1 and 2;

FIG. 16 is a schematic circuit diagram showing the electromechanical means used to detect when more than a single carrier sheet or sample has been fed, and to deflect such multiple items from the normal path followed by single items and into a reject hopper;

FIG. 17 is a generally schematic, plan illustration of the drive arrangement for the apparatus as depicted in FIGS. 1 and 2;

FIG. 18 is a diagrammatic side elevational view of an alternate main conveyor arrangement; and

FIG. 19 is a diagrammatic side elevational view of alternate platen means for supporting carrier sheets at the affixing point and also illustrates upper and lower squeeze belt means.

GENERAL

Generally speaking, this invention is directed to an apparatus for applying and affixing an article or sample to a carrier sheet as a high speed, automatic operation. The apparatus includes a magazine containing a plurality of the carrier sheets; means for separating and feeding individual carrier sheets in timed, spaced relationship along a main conveyor surface; a magazine containing a plurality of the samples or articles which are to be affixed onto the carrier sheets; means for separating and feeding individual samples from the sample magazine in timed relationship; sample-conveying means, including timed means for bringing each such sample into register with a predetermined position on one of the carrier sheets; and including a sample transfer mechanism positioned between the sample conveyor and the main conveyor surface for applying and affixing the samples to the carrier sheets at a fixed, preselected position thereon.

The carrier sheet magazine and the sample magazine, together with the separating and feeding mechanisms for both carrier sheets and samples, are preferably both so constructed that both carriers and samples may be added to the respective magazines without stopping or interrupting the continuous operation of the machine.

Means are provided for applying an adhesive to each sample as it is transferred into position to be affixed to the carrier sheet that is to receive it. Means for conveying the combined carrier sheet and affixed sample to a delivery point, together with delivery means for receiving the combined units, completes the basic components of the apparatus. Means for folding the carrier sheets once or more than once after the samples have been affixed, may, if desired, be incorporated between the point where the sample is affixed and the delivery means.

In order to more fully understand and comprehend the herein disclosed invention, it will be necessary to consider in some detail each of the functions performed by the apparatus as a single entity. For instance, the separating and feeding of the carrier sheets, the conveying of the same on an endless conveyor, the separating and feeding of samples (or printed forms), etc., lend themselves to be broken down and analyzed for descriptive purposes so that this disclosure is more meaningful and understandable. The disclosures, therefore, will be made in this manner after the basic, overall description of the apparatus has been set forth which generally can be gleaned from FIG. 1 of the drawings.

OVERALL APPARATUS AND OPERATION

Referring specifically to FIG. 1, the automatic, sample-affixing machine 26 is shown as comprising a base or support structure 27 on which are mounted side frame members 28 through which shafts are journaled and other components secured. At the extreme right-hand of the apparatus, there is schematically shown a feeder 29 for carrier sheets which may be a modified version of a feeder such as disclosed in Anderson et al. U.S. Pat. Nos. 2,954,976 and 3,032,338. The specifics of this feeder, or other feeders for carrier sheets that may be utilized in conjunction with the automatic sample affixing apparatus 26, will be delved into in more detail hereafter.

10 The major components of the automatic sample-affixing apparatus 26 comprise a main, or carrier sheet, conveying surface 30 which, in this instance, is of dual configuration.

To insure that the carrier sheets (not shown) move through the machine in proper timed relationship and are positioned

20 for the remainder of the operations to be performed, one or more lugged chains 32, carrying uniformly spaced lugs 33, are provided which are driven positively at a surface speed which is coordinated with the surface speed of other elements of the machine, as will be described. Belts or tapes 31, supported

25 from below, are also utilized to transport the individual carrier sheets, fed thereon from the carrier feeder end of the machine 26, through the machine to the opposite or delivery end of the machine. This portion of the main conveyor comprises, in this instance, a plurality of tapes 31 moving at a surface speed

30 which is faster than the surface speed of the lugged chains 32. Because the carrier sheets are fed onto the tapes 31, which are moving at a faster speed than the lugged chains 32, the leading edge of each carrier sheet will be carried into contact with one (or an aligned pair) of the lugs 33 and thereafter held in contact with the lug (or lugs) 33 and thereby positioned in proper relationship for further operations as it moves through the machine.

35 Skid rails 64 carrying diagonal and/or straight, free-turning rollers (not shown) rest on top of the carrier sheets above the conveyor tapes 31 and hold the carrier sheets in contact with the tapes 31 and with one of two side guides 98.

40 Superposed and supported by the side frame members 28, or on a separate supporting frame or stand of its own, is a hot-melt glue unit 34 of conventional construction, which, upon actuation, directs a stream of hot glue toward a target, which in this case is the sample to be affixed to the carrier sheets. The specifics of this component of the apparatus, as well as its mode of operation and how it is tied into the overall control system, will be gone into in further detail later on.

45 Mounted above the carrier conveying surface 30 of the automatic sample-affixing apparatus 26, is a sample transfer wheel 35 which is slideably mounted on, and rotates with, shaft 13 which is journaled in side frames 28. Wheel 35 is the

50 rotating member of the sample transfer, applying and affixing device, and is a disc-shaped member having four suction heads 38 mounted 90° apart at its periphery. The sample transfer wheel 35 rotates in the direction of the arrow and is adapted to apply vacuum to pick a sample from the registered position

55 153 on the sample conveyor 40, positioned above member 35, and to carry it by means of one of the suction heads 38, through a curvilinear path 151, during which time the hot-melt glue unit 34 is actuated to squirt a stream of hot glue on the underside, or outer exposed surface, of the sample 41. The

60 sample transfer wheel 35 is driven in timed relationship with the lug-carrying chain (or chains) 32 and at a speed which causes the outer surface of a sample carried by one of the suction heads 38 to move at the same surface speed as the lugs 33 carried by the chain (or chains) 32. The sample transfer wheel 35 continues carrying the sample 41 to a position 154 directly

65 above the carrier sheet conveyor 30 where it encounters a carrier sheet, such as an envelope. At the point 154, the underside of the carrier sheet is supported by a platen roller 112, which is laterally positioned between the tapes 31, and the chain or chains 32, and in line with the position on the carrier

sheet to which the sample is to be affixed. The platen roller 112 is either free to rotate at the surface speed of the carrier sheet or is driven at the same surface speed as the carrier sheet. At this point 154 the sample 41 is pressed onto the surface of the carrier sheet by the suction head 38, carried by the sample transfer wheel 35, and the vacuum is simultaneously discontinued, thereby releasing the sample to the carrier sheet, which is supported from below by the platen roller 112. Because of the glue and/or other adhesive forces, the sample is secured to the carrier sheet which is being carried therealong on the carrier tapes 31, with its leading edge held in contact with the lug or lugs 33 on the chain or chains 32. The surface speed of the carrier sheet is thus identical to the surface speed of the bottom surface of the sample carried by the sample transfer wheel 35, at the time the transfer is being made.

Stripper fingers 226 on either side of the transfer wheel 35 insure that the sample 41 will not be carried beyond point 154 by the suction head 38.

If desired, the carrier sheet, with the sample affixed, may then be carried through pinch rollers, or upper and lower squeeze belts, and/or into either a delivery area or the bite of rollers of a modified conventional sheet folder.

Referring back to the carrier sheet feeder end of the machine, there is positioned above the carrier sheet conveyor a sensing means 42 to detect for the presence or absence of a carrier sheet or envelope. The distance, from the sensing means 42, to the point of tangency 154 between the carrier sheet conveyor and the curvilinear path 151 described by the outer surface of a sample carried by one of the suction heads 38 on the sample transfer wheel 35, is equal to the circumferential distance traveled along path 151 by a sample 41, carried by one of the suction heads 38, from the point 153, where the sample is picked up from the sample conveyor, to this same point of tangency 154. A signal from sensing means 42 is fed through a circuit such as that shown and described in FIG. 15, and thereby controls the position of the sample reject fingers 46. Since the outer surface of a sample 41, carried by one of the suction heads 38 on the sample transfer wheel 35, travels at the same surface speed as a carrier sheet moving along the carrier sheet conveyor, with its leading edge held in contact with one, or a pair, of the lugs 33, the position of the sensing means 42 as described above, together with the position of the dwell in the timing cam 180 as shown and described in connection with FIG. 15, causes the sensing means 42 to detect for the presence or absence of a carrier sheet only at the time when the sample to be applied to that carrier sheet would be in position to be picked from the product conveyor 40 by one of the suction heads 38, of the sample transfer wheel 35. It should further be noted that at the time this sensing action takes place, the area of the carrier sheet to which the sample is to be affixed will be directly in line with the sensing means 42, if such a carrier sheet is present.

One form of the sample feeder component or assemblage 90 of the machine 26 comprises a reciprocating suction shuttle blade 67 utilizing suction to remove one sample at a time from the supply in the magazine 43. The sample is fed between parallel upper and lower conveyor belts 44 and 45 to a point where it is stopped by stop fingers 39 and positioned to be removed by one of the rotating suction heads 38, upon its rotation into contact with the waiting sample.

If a carrier sheet has been properly fed and is detected by the sensing means 42, the sample will be allowed to be carried by the suction head 38 all the way around path 151 to the position 154 where it is affixed to the carrier sheet; whereas if the sensing means 42 has detected that no carrier sheet is present, stripper fingers 46 will move down into the position shown in FIG. 2 and strip the sample from the suction head 38 and divert it to a cross conveyor 47 which spans the machine, whereby it is carried to a catcher pan (not shown) at the side of the machine.

The sensing mechanism for actuating the hot-melt unit 34 is a photoelectric one designed to be actuated by the passage of a sample, carried by a suction head 38 on the sample transfer

wheel 35, through a light beam which is located beyond the point at which a sample is removed from the suction head 38 by the stripper fingers 46 in the absence of a carrier sheet. It is apparent, therefore, that in the absence of a sample passing through the light beam, the hot-melt unit 34 will remain inactive and will not squirt glue, when a sample is not present, onto the suction head 38 as it passes the position of the light beam.

Moving further along the machine, after the position 154 is passed, at which a sample would normally be affixed to the carrier sheet, the carrier sheet continues to another sensing means 48 which senses for the presence or absence of a sample affixed to the carrier sheet in the proper position. If a sample is not present in the proper position on the carrier sheet, a deflector gate 49 opens and diverts the carrier onto a reject conveyor 114 which conveys the carrier to a catcher pan or reject receptacle 50 positioned for that purpose.

Preferably, as the carrier sheet passes beyond the position 154 at which a sample is normally affixed to the carrier sheet, the carrier sheet and the affixed sample pass between upper and lower squeeze tapes (not shown) which are positioned vertically above one another at the position across the carrier sheet at which the sample is affixed. These upper and lower squeeze tapes are supported from above and below throughout their length and are driven at the same surface speed as the lugs 33 carried by the chain 32. These upper and lower squeeze tapes perform the function of holding the sample in firm engagement with the carrier sheet as the carrier sheet is conveyed to the delivery end of the machine, and during which time interval the glue has time to set, so that the sample is firmly affixed to the carrier sheet by the time the carrier reaches the delivery end of the machine. They perform the further function of holding the affixed sample firmly in position on the carrier sheet as it passes the detector 48, so that the action of the detector 48 in sensing for the presence or absence of a sample does not disturb the position of the sample on the carrier sheet, even though, at that point, the glue may not yet have set sufficiently to, of itself, hold the sample in position against the force of the detector 48. These upper and lower squeeze belts are adjustable with respect to their distance from one another so that they may be adjusted to exert just the proper squeezing pressure on any given combination of carrier sheet and sample thickness.

The position of the detector 48 is also adjustable along the length of the main conveyor, along mounting rails 227. Its position is adjusted by first moving a carrier sheet into position, with its leading edge in contact with one of the lugs 33, to a point sufficiently ahead of the deflector gate 49 so that the deflector gate 49 will have ample time to open or close, in response to a signal from the detector 48, before the leading edge of the carrier sheet reaches the deflector gate 49, at the speed at which the machine is to be operated. The detector 48 is then moved into position so that it is above the position on the carrier sheet at which a sample is to be affixed and the detector 48 is then secured in this position. Both the upper and lower squeeze belts and the detector 48 are adjustable from side to side across the width of the carrier sheet and are normally positioned so that the upper and lower squeeze belts are in line with that position on the sample to which the glue has been applied, and the detector 48 is positioned alongside the upper squeeze belt (or between a pair of upper squeeze belts), in which position it acts to sense the presence or absence of a sample by contacting a portion of the sample which is not held between the upper and lower squeeze belts. The detector 48 is adjustable to detect various thicknesses and is set so that the presence of a carrier sheet with a sample affixed thereto in the proper position, and at the proper time in the cycle of the machine, will actuate the detector to indicate the presence of a sample affixed to the carrier sheet, whereas a carrier sheet alone, without a sample affixed thereto (or the absence of both the carrier sheet and sample), will be detected as the absence of a sample. The detail of the circuitry by means of which the detector 48 controls the deflector gate 49 is illustrated and described hereafter in connection with FIG. 15.

It should be noted that in cases where the carrier sheet is to be folded once, or more than once, after the sample has been affixed thereto, the carrier sheet is delivered into the folding machine after it passes over the deflector gate 49. Since any carrier sheets which do not have samples affixed thereto are deflected by the deflector gate 49 into the reject hopper 50, only carrier sheets which do have samples affixed thereto in the proper position pass over the deflector gate 49 and into the folding machine. This insures that all carrier sheets emerging from the folding machine do, in fact, have samples affixed thereto, even though after the fold or folds have been made this fact may not be easily determined by visual inspection, and, further, it insures that all carrier sheets which do not have samples affixed thereto are deflected into the reject hopper 50 without being folded, and they can then be placed again in the carrier sheet feeder 29. Similarly, samples which have been ejected by the stripper fingers 46, onto the cross conveyor 47 and thereby into the catcher pan at the side of the machine, because of the absence of a carrier sheet to which to affix such samples, are similarly undamaged and may in turn be loaded again into the hopper 43 of the sample feeder 90.

The motor 51 and speed reducer 52 along with the connecting chains and timing belts, generally designated 53, indicate the manner in which the apparatus 26 and feeders 29 and 90 are powered. The vacuum pumps required for the various suction components of the apparatus are not shown, as well as various specific details of construction, since at this point it is intended to merely describe the overall operation of the machine utilizing the somewhat schematic drawing of FIG. 1. Having disclosed the overall, basic structure, the functioning of same and the objects to be pursued and attained, a more detailed discussion and description will be made hereinafter vis-a-vis various specific assemblages and components of parts for accomplishing each one of the series of functions necessary to obtain the desired results.

CARRIER SHEET FEEDER

As indicated earlier, the feeder 29, which separates individual carrier sheets, (taking the form of a brochure, a signature, an advertising folder, a sheet of paper or cardboard, or an envelope, etc.) from a stack of such carrier sheets and delivers or conveys such individual carrier sheets onto the main conveyor 30 of the automatic sample-affixing machine 26 may be any one of a number of automatic feeders well known in the art. Obviously the feeding of carrier sheets may be manual, but in order to achieve all of the objects of the invention, it is preferred to use an automatic feeder, which may be similar to that illustrated in Anderson et al. U.S. Pat. Nos. 3,032,338 and 2,954,976, modified to some degree as will be hereinafter discussed in reference to FIGS. 6 to 13 inclusive.

The basic structure of the automatic sample affixing machine 26 is modular, and different types of carrier feeders may be utilized depending upon the application for which the overall machine is to be utilized. When the machine is to be utilized primarily for affixing samples to carrier sheets which consist of individual, relatively thin sheets of paper, an automatic pile suction feeder similar to that illustrated in Davidson U.S. Pat. No. 1,963,694 may be utilized to advantage as a carrier sheet feeder, since a relatively large number of such individual carrier sheets may be loaded into such a feeder on a single loading, and it will thus be necessary to stop for reloading only at relatively infrequent intervals. On the other hand, if the carrier sheets are relatively thick, such as brochures, signatures, booklets, etc., or if they are materials such as flap-extended envelopes which will not stack uniformly, so that, in either case, only a comparatively small number of carrier sheets may be loaded at one time, it is then desirable that the feeder used be of a type into which carrier sheets may be loaded continuously, as the machine runs, without having to stop to reload.

For present purposes, and referring to FIG. 1, carrier sheets are loaded continuously into hopper 58 of shuttle-type feeder 29 which obtains its drive:

- a. Via a chain, not shown in FIG. 1, connecting sprockets on shaft 16 and on shaft 17;
- b. From a crank arm, not shown in FIG. 1, at the end of shaft 11; and
- c. From a chain 54 connecting one of several sprockets generally designated 55 on shaft 18 of speed reducer 52, to a sprocket 288 on shaft 22. Reciprocating vacuum shuttle blade 56 feeds carrier sheets, such as envelopes, individually to the bite of upper and lower pullout rollers 57, positioned to receive the leading edge of a carrier sheet advanced to them by the vacuum shuttle blade 56. A lifter mechanism 59 periodically lifts the stack of carrier sheets so as to facilitate individual feeding thereof. Details of the shuttle feeder and the modifications that may be made to facilitate trouble free individual feeding of carrier sheets of various types will become apparent in relation to the specific discussion of the somewhat similar feeding mechanisms depicted in FIGS. 2, 6, 7, 8, 9, 12, 13 and 14.

THE CARRIER-SHEET-CONVEYING SYSTEM

Still referring to FIG. 1, once the carrier sheet is fed to the bite of the carrier feeder pullout rollers 57, it is pulled from the bottom of the stack of carrier sheets by these rollers and delivered by them onto a plurality of spaced flexible tapes 31 spanning almost the entire length of the machine 26. The tapes 31 pass over a driven roller 60 at the carrier feeder end of the machine and an idler roller 62 near the delivery end of the machine. The tapes are kept taut by the action of a series of tape tightener rollers 99, which are idler rollers adjustably mounted so that they may be moved to increase or decrease the tension of the tapes. The top surface of the tapes 31 is supported from sagging, throughout their length, by supporting rails 61, one of which rails is located under the upper run of each of the tapes 31. The tapes are driven, by the driven roller 60, at a surface speed somewhat faster than the speed of the lugs 33 carried by the chains 32. One, or a pair, of chains 32 carrying spaced lugs 33 are positioned laterally across the machine between the flexible tapes 31. The top surface of the chains 32 lies below the plane of the top surface of the flexible tapes 31, but the lugs 33 carried by the chains 32 project upwardly, above the level of the top surface of the tapes 31.

The machine may be adjusted to handle carrier sheets of different length, up to a maximum length which is somewhat less than half the circumference 151 of the sample transfer wheel 35 (measured at the outer surface of a sample 41 carried by one of the suction heads 38 on the transfer wheel 35).

When carrier sheets somewhat shorter than one quarter of the above-described circumference 151 of sample transfer wheel 35 are being handled, the lugs 33 are spaced apart from each other on chain 32 by a distance exactly equal to one quarter of the above-referenced circumference 151 of sample transfer wheel 35; and in this case both the carrier feeder 29 and the sample feeder 90 are adjusted to feed four carrier sheets and four samples, respectively, for each complete revolution of sample transfer wheel 35. This is referred to as "double-lugged" operation.

When the carrier sheets being handled are longer than approximately one quarter of the above-referenced circumference 151 of sample transfer wheel 35, the lugs 33 carried by the chains 32 are spaced apart by a distance exactly equal to one-half the above-referenced circumference 151 of sample transfer wheel 35. In this case, both the carrier feeder 29 and the sample feeder 90 are normally adjusted to feed two carrier sheets and two samples, respectively, for each complete revolution of the samples transfer wheel 35. This is referred to as "single-lugged" operation.

The length of the lug-carrying chains 32 is an exact whole multiple of one-half the above-referenced circumference 151 of sample transfer wheel 35. Each of the lug carrying chains 32 is carried by a driving sprocket 63 on shaft 16 and a driven sprocket 100 on shaft 21. And each chain is kept taut by the action of an idler tightener sprocket 106, whose position may be adjusted to control the tautness of the chains. Both shaft

16, on which the driving sprockets 63 for the lug-carrying chains 32 are mounted, and shaft 13 of sample transfer wheel 35 are driven by positive means, including chains and/or timing belts and sprockets and gears in such a manner that the surface speed of the sample transfer wheel at the above-referenced circumference 151 is identical to the surface speed of the lugs 33 carried by the chains 32.

Each carrier sheet is fed onto the tapes 31 in timed relationship with the passage of the lugs 33, carried by the chains 32, in a manner so as to place it between adjacent, spaced lugs 33. To insure sufficient frictional driving contact between the carrier sheets and the tapes 31, a "skid rail" 64 is mounted above each tape 31. Each of these skid rails 64 is supported at the end of the conveyor adjacent the carrier feeder pullout rolls 57 and lies in contact with one of the tapes 31 throughout its length, guided from above at various points throughout its length to insure its alignment with the tape 31 on which it rests. The "skid rails" 64 are elongated springlike straps generally carrying a series of rollers (not shown) mounted therein throughout their length. In some cases, the axes of these rollers are at right angles to the length of the straps and the rollers simply lie on top of the tapes, or on the top surface of carrier sheets being conveyed by the tapes. The rollers idle and the weight of the tapes and the rollers acts to hold the carrier sheets in frictional contact with the top surface of the conveying tapes 31. At least one of the skid rails 64, which is mounted above the tape 31 which is adjacent one of the side guides 98, carries idler rollers which lie with their axes diagonal to the length of the skid rail, and inclined in a direction so that they will act to cause carrier sheets, on which they rest as the carrier sheets pass beneath them, to be urged to one side, in the direction of the adjacent side guide, thus causing the side edge of the carrier sheet to be first urged into contact with the adjacent side guide, and then held in sliding contact with the side guide throughout the passage of the carrier sheet along the conveyor. The rollers in the skid rails 64 are not illustrated inasmuch as they are well known in the art and are commercially available for the purposes just described.

After a carrier sheet is fed onto tapes 31, in a manner so as to place it between two adjacent spaced lugs or pairs of lugs 33 carried by the chains 32, and has passed under the leading portion of the skid rails 64, the higher surface speed of the conveyor tapes 31 will carry the leading edge of the carrier sheet into contact with the edge of the leading lug or pair of lugs of the two between which it has been placed, and the action of the diagonal rollers in one or more of the skid rails will cause a side edge of the carrier sheet to be brought into contact with the adjacent side guide 98. As the carrier sheet is conveyed on through the machine, it will thereafter have that side edge kept in sliding contact with the adjacent side guide by the continuing action of the diagonal rollers in one or more of the skid rails, and it will have its leading edge kept in contact with the lug or pair of lugs by the frictional drive of the conveyor tapes 31, which continue to move faster than the lugs 33 and thereby continually hold the leading edge of the carrier sheet snugly in contact with the lug or pair of lugs 33.

At times, irregularities in the carrier sheets themselves, or in the manner in which they are loaded into the magazine 58 of the carrier sheet feeder 29, may interfere with the feeding of individual carrier sheets in exact timed relationship with the lugs 33; so that in such cases such a carrier sheet, instead of being positioned between adjacent spaced lugs or pairs of lugs 33, may be delivered onto the conveyor in such a manner that either its trailing or leading edge lies on top a lug or pair of lugs. A carrier sheet that is delivered onto the conveyor with its trailing edge lying atop a lug or pair of lugs will be pulled forward by the combined action of the faster moving tapes 31 and the skid rails 64 and its trailing edge will thus be pulled off the following lug or pair of lugs, and its leading edge will be advanced into contact with the lug or pair of lugs ahead, as described above.

To provide for the case in which such a carrier sheet is delivered onto the conveyor 30 with its leading edge on top of a lug or pair of lugs, one or more fingers 65 are mounted above the conveyor 30, in a fixed position, extending downwardly below the level of the top of the lugs 33 but still above the path of a carrier sheet conveyed by the tapes 31 which has been properly spaced between two adjacent lugs or pairs of lugs, and which does not have its leading edge on top of a lug or pair of lugs. Such a properly placed carrier sheet will, therefore, pass along the conveyor below these fingers 65 and without being contacted or disturbed by them. However, an improperly placed carrier sheet, the leading edge of which lies on top of a lug or pair of lugs, will contact these fingers 65, and be held back by them, until the lug or pair of lugs passes on ahead of the leading edge of the carrier sheet. As soon as the lug or pair of lugs have passed out from below the leading edge of the carrier sheet, the weight of the skid rails resting on top of the carrier sheet will immediately cause it to drop into position on the tapes 31, between the lug or pair of lugs on which its leading edge previously rested and the following lug or pair of lugs carried by the chains 32. The leading edge of the carrier sheet will thus drop free of the fingers 65 and the faster speed of the tapes 31 will thereupon act as described above to bring the leading edge of the carrier sheet into contact with the lug or pair of lugs ahead, and the sheet will proceed along the main conveyor 30 in proper fashion as previously described.

Other alternate means may be employed for conveying the carrier sheets through the machine along the main conveyor in registered and timed relationship with other elements of the machine.

For instance, the tapes 31 may be driven at a speed slower than the lug-carrying chain or chains 32 and in this instance a lug or pair of lugs 33 would catch up with the trailing edge of a carrier sheet, delivered onto the conveyor 30 as previously described, and in this instance the carrier sheet would thereafter be pushed through the machine along the conveyor 30 by the action of the lug or pair of lugs 33 against its trailing edge.

Another and preferred alternate means of conveying carrier sheets through the machine on the main conveyor in timed relationship with other elements of the machine is to replace the tapes and lug-carrying chains described above with a series of cogged timing belts as illustrated diagrammatically in FIG. 18. Referring to FIG. 18, the cogs on the inner surface of timing belts 307 mesh with the teeth of timing belt sprockets 304 and 305 and are thus driven in timed relationship with the other elements of the machine. Timing belt sprocket 305 takes the place of both tape roller 60, and chain sprockets 100 on shaft 21, of FIG. 1, and it is located in the position of tape roller 60 but driven as described for sprockets 100 on shaft 21. Timing belts sprocket 304 is the driving sprocket and it takes the place of both tape roller 62 and the chain sprockets 63, on shaft 16, of FIG. 1, and is located in the position of tape roller 62 but driven as described for sprockets 63 on shaft 16.

The timing belts 307 span the entire length of the main conveyor 30. The outer flat surface of these timing belts 307 acts as the conveying surface for the carrier sheets and moves at a surface speed identical with the surface speed of circumference 151 of sample transfer wheel 35. Timing belts 307 are kept taut by idler timing belt tightener sprockets 306 in a manner similar to that previously described with respect to the tapes and chains. Similarly, the upper run of these timing belts 307 is supported from below, to prevent them from sagging, by support rails 309, 310 and plate 311. At least some of the timing belts 307 carry rubber stops, or lugs, 308 vulcanized to their outer flat surface, and spaced apart exactly as described for the lugs 33 carried by the chains 32. Similarly, the length of the timing belts 307 is an exact multiple of one-half the above circumference 151 of the sample transfer wheel 35. A carrier sheet delivered onto the conveyor 30 between two adjacent lugs or pairs of lugs 308 is held back by a brush 322, or other slowdown device, which contacts the leading edge of a

carrier sheet and holds it back until its trailing edge has been contacted by one of the lugs or pairs of lugs 308, which then push the sheet forward, and the sheet is thereafter conveyed on the upper flat surface of the timing belts 307, moving at the same speed as the belts themselves, and with its trailing edge in register-contact with the following lug or pair of lugs 308. One side of the sheet is brought into register with the adjacent fixed side guide by means of a series of light flexible flat springs, acting upon the opposite side of the carrier sheet and urging it into contact with the side guide. In addition, hold-down straps or rails may be mounted above the sheets, between the timing belts 307 which carry lugs 308, above the timing belts 307 which do not carry lugs, to hold the sheet flat on the surface of the timing belts 307.

For each stream of carrier sheets there are at least two of the lugged timing belts 307 and between two of these lugged timing belts 307, and in line with the area of the carrier sheet to which a sample is to be affixed, there is another timing belt 313, as seen in FIG. 19. The outer surface of timing belt 313 is smooth and flat and there are no lugs attached thereto. Timing belt 313 also passes around and meshes with timing belt sprocket 304 and is driven thereby and it also encircles another timing belt sprocket 314 which is located between the timing belt sprocket 305 and the affixing point 154. Timing belt 313 is kept taut by a tightener sprocket 315. Since the lugged and the unlugged timing belts 307 and the timing belt 313 without lugs are all driven by the same timing belt sprocket 304, their surface speed is identical. The upper run of timing belt 313 is supported from below by rails 309 and plate 311. Plate 311 extends across the width of the machine under the lugged and unlugged timing belts 307 and the smooth timing belt 313 and plate 311 is in turn supported on two eccentric shafts 312 by means of which it may be raised or lowered. Timing belt 313, which is under the area of the carrier sheet to which a sample is to be affixed, acts as a platen surface and supports the carrier sheet under the affixing point 154. Since the timing belt 313 is itself supported at this point on the plate 311 and the plate 311 may be adjusted up or down by means of the eccentric shafts 312 on which it is mounted, adjustments may thus be made to compensate for different thickness of carrier sheets at the affixing point 154.

As also seen in FIG. 19, there is another timing belt 320 positioned directly above belt 313 and which extends from just beyond the sample transfer wheel 35 to a position above timing sprocket 304. This upper timing belt 320 is supported on a driven timing belt sprocket 317 and an idler timing belt sprocket 316 and kept taut by two tightener sprockets 318 and 319. The lower run of timing belt sprocket 320 is supported from above by a backup rail 321, which may be adjusted vertically up and down to increase or decrease the spacing between the lower face of timing belt 320 and the upper face of timing belt 313. These two timing belts 313 and 320 thus form squeeze belts, from the position of sprocket 316 to the position of sprocket 317, and as a carrier sheet with a sample affixed thereto passes between these belts they act to squeeze the sample onto the carrier sheet and to hold it in intimate contact with the carrier sheet as the carrier and the affixed sample are conveyed to the delivery end of the machine. The timing belt 320 is driven so that its surface speed is identical to the surface speed of timing belt 313 and since the backup rail 321 can be adjusted vertically, the pressure with which the sample is squeezed against the carrier sheet may be adjusted and the sample is held securely in position while the glue has time to set.

The upper squeeze belt 320 may be a single belt or two belts side by side and in either case the belt or belts 320 are located so that they are in position above the area of the bead or beads of glue by which the sample is adhered to the carrier sheet.

The detector 48, mounted as previously described, is so located from side to side that it will contact a portion of the sample as it passes the position of the detector 48. The detector may thus contact the center portion of the sample between two squeeze belts 320 or an edge of the sample which extends

beyond the side of a squeeze belt 320. At the time that the sample affixed to the carrier passes the position of the detector 48 it is being held firmly in contact with the carrier sheet between the upper and lower squeeze belts 320 and 313 and this prevents the detector from moving the sample on the carrier sheet as the sample acts to lift the detector, even if the glue has not yet set firmly.

The detector 48 may be positioned at any point along the mounting bar 227 as is described in more detail elsewhere herein.

SAMPLE FEEDER

Referring to FIG. 2 and FIG. 2A, the sample feeder assembly or component, generally designated 90, of the automatic sample affixing machine is shown as having end frame members 119 mounted to angle support frames 66 which are in turn mounted on the main frames 28 of the automatic sample affixing machine 26 proper. This sample feeder component of the machine comprises two major portions: the first of which generally includes the sample magazine, generally designated 43, plus the reciprocating shuttle blade 67, which in combination with the gate 69 separates and feeds individual samples from the magazine 43 into the bite of upper and lower pullout rollers 70 in timed relationship with the other operating functions of the machine as a whole; and the second, comprising the sample conveyor, generally designated 40, including upper and lower sample conveyor tapes 44 and 45 respectively, which conveys the sample, registers it and presents it at the proper time and place to be picked up by one of the rotating suction heads 38 on the sample transfer wheel 35, in uniformly registered relationship to the rotating suction head 38.

The sample magazine 43 comprises a series of upstanding, preferably movable and adjustable, bars and angles 68 secured to supports which are in turn secured to the side frame members 119. The front magazine bar 120 in the forward portion of the magazine 43, nearest the conveyor, also carries a vertically adjustable member, which acts as a gate, 69 to allow only a single sample to be passed between it and the reciprocating shuttle blade 67 to the bite of the pullout rollers 70. The reciprocating shuttle blade 67, having vacuum connection through hose 71, is caused to reciprocate in linear fashion by movement of shuttle slide rod 72, to which it is adjustably fastened, and which in turn is given a reciprocating motion by associated linkage 73 to which a rocking motion is imparted by a stud 275 mounted eccentrically in disc 274 at one end of shaft 12. The detail of the shuttle mechanism will be delved into in more detail later, but for present purposes, suffice it to say that the shuttle 67 in combination with the gate 69 normally accomplishes the separation and feeding of one sample at a time. In order to aid in the feeding of individual samples, a lifter mechanism 76 is provided which lifts the stack of samples in the magazine out of contact with the shuttle blade 67 on the return stroke of the shuttle blade 67. The operation of the lifter mechanism 76 and the function it performs in the separation of individual samples will also be described hereafter in greater detail. Vacuum is drawn in the face of the shuttle blade 67 which contacts the face of a sample, during the forward stroke of the shuttle blade, so that the bottom sample in the stack is held in contact with the shuttle blade 67 throughout its forward stroke, thereby drawing a single sample through the space between the gate 69 and the shuttle blade 67 and presenting the leading edge of the sample into the bite of the upper and lower pullout rollers 70. At this point the suction in the connector hose 71 is cut off, thus releasing the sample from the surface of the shuttle blade 67 and the sample is pulled out, from the bottom of the pile of samples, by the action of the pullout rollers 70, which in turn deliver the sample onto the sample conveyor 40 between the lower conveyor tapes 45 and the upper conveyor tape 44. The return stroke of the shuttle then returns the shuttle blade 67 to its original position beneath the stack of samples in the magazine 43. At this point a vacuum is again drawn in the shuttle blade 67 through

the hose connector 71 and the process is repeated. The actuation of the vacuum control for this separate vacuum system is accomplished by means of a solenoid-actuated valve in the hose connector line 71 which leads to a separate vacuum pump; the action of this valve is in turn controlled by a microswitch and a dual, or split, cam on a cam shaft which rotates in timed one-to-one relationship with the cycle of the shuttle in control box 273 (seen in FIG. 17). It is thus possible to accurately adjust and control the time at which a vacuum is first drawn in the suction shuttle blade 67, when it reaches the backward end of its stroke, and also to separately control and adjust the time at which the vacuum is broken to release the sample, at the time in the forward stroke of the shuttle blade 67 when the leading edge of the sample is seized by the pullout rollers 70.

SAMPLE CONVEYOR

The conveyor portion 40 of the sample separating and feeding assemblage 90, onto which the sample is then delivered by the pullout rollers 70, comprises two pairs of supporting side frames, upper side frames 79 and lower side frames 148 respectively. The upper side frames 79, are secured to the up-standing portions 80 of the main frames 28 of the machine proper, at one end, and are supported at the other end by shaft 20 on which they are journaled and which is in turn journaled in the main frames 119 of the sample feeder proper. The lower conveyor side frames, 148, are tied together by two cross members, round spreader bar 81 and square spreader bar 142, and in addition, lower frames 148 are journaled to pivot about shaft 20 adjustably with respect to the upper pair of conveyor frames, 79, by means of I-bolts 147, which are adjustably mounted to frames 79 and support the ends of shaft 81, adjacent the forward ends of the lower conveyor frames 148. The stems of these I-bolts 147 pass through blocks carried by the upper conveyor frames 79 and are adjustably secured with respect to these blocks by upper and lower lock nuts on each I-bolt 147. Each individual lower conveyor tape 45 encircles and is supported by, a driving tape roller 150 (which extends across the width of shaft 20) and an individual forward idler tape roller 126, which is only slightly wider than the individual tape 45. Each forward idler tape roller 126 is individually journaled at the forward end of a forwardly projecting cantilever support finger 143, each of which is adjustably mounted on the two cross members 81 and 142, and is held in position thereon by a clamp bolt 149 which clamps it against the cross member 142. The individual forward idler tape rollers 126 are therefore each held in cantilever fashion at the forward end of each individual cantilever support finger 143, so that one or more pairs of lower conveyor tapes 45 may be placed with one tape in each pair on opposite sides of sample transfer wheel 35 while still allowing the suction heads 38, carried by the sample transfer wheel 35, to pass between a pair of the lower conveyor tapes 45 without interference.

The upper surface of a sample, as it is carried on the tapes 45, passes along a plane tangent to the previously described circumference 151 of sample transfer wheel 35, and the length of the cantilever support fingers 143 in such as to place the center of the forward idler tape rollers 126 on a radial line drawn from the center of the sample transfer wheel 35, perpendicular to this plane of tangency. Each one of a pair of these cantilever support fingers 143 carry, respectively, right and left hand angular side guide members 84 affixed to their upper surface and these angular side guide members extend approximately from driven roll 150 to idler rollers 126. The horizontal portions of these angular members act as supporting rails for the lower conveyor tapes 45, throughout most of their length, and the vertical sides of these angular members 84 act as right and left side guides, to accurately position each sample laterally as it is conveyed along the conveyor tapes 45. When the samples are relatively narrow a single pair of lower conveyor tapes 45, thus supported, will be used for each sample transfer wheel 35, as illustrated in FIG. 2A. In cases where

the samples are relatively wide an additional pair of lower conveyor tapes 45 may be used, with one additional tape being placed on each side of the sample transfer wheel 35. In this case, the support fingers 143 which are closest to the sample transfer wheel 135 will have the angular side guide members 84 replaced with simple flat members, which will act only as supporting rails under that pair of lower conveyor tapes 45. A tape tightener bar 96 is provided to take up the slack in the lower conveyor tapes 45 and keep them taut; and tape guides 144 are positioned along this tape tightener bar 96 to guide each of the lower conveyor tapes 45 and hold it in position laterally. The side to side position of the lower conveyor tapes 45 may be adjusted by loosening the clamp bolts 149, which hold the individual cantilever support fingers 143 in position, and the fingers 143 may then be moved from side to side and refastened in the desired position. The tape guides 144 are movable from side to side along the tape tightener rod 96 and may be similarly adjustably positioned. The driven tape roller 150 extends across the entire width of the feeder and the tapes may therefore be moved to any position across the width of this roller.

The upper conveyor tapes 44 are carried by a driven roller 83, journaled on a shaft 82 which in turn is adjustably supported from the main frames of the feeder 119 by means of a pair of adjustable arms, and a forward idler tape roller 146, journaled on a shaft 123 at the forward end of upper conveyor frames 79. Tape rollers 83 and 146 both extend across the full width of the sample conveyor and are so positioned that the lower surface of the upper conveyor tapes 44 will lie approximately along a plane tangent to the previously described circumference 151 of sample transfer wheel 35. As will be seen in FIG. 2, the forward tape roller 146 is positioned well beyond the point of tangency between this plane and the previously described circumference 151 of sample transfer wheel 35. A tape tightener rod 95 is provided for taking up the slack in the tapes and holding them taut, and tape guides 144, similar to those previously described, are used to adjustably position the tapes laterally across the width of the sample conveyor. Generally, a single upper conveyor tape 44 is used for each sample transfer wheel 35, with the tape positioned laterally to be directly above the suction heads 38 carried by the sample transfer wheel 35 and therefore between the inner pair of lower conveyor tapes, which are located as previously described on either side of the sample transfer wheel 35.

Shaft 20 is driven, in the direction shown, by means of a sprocket 256, affixed to one end of the shaft, which sprocket in turn is driven by a chain 257 from another sprocket 255 on the end of shaft 13 (as seen in FIG. 17). At one side of feeder 90, just inside feeder frame 119, there are sprockets on the shafts on the upper and lower pullout rollers 70. There are also sprockets on shaft 20 and on roller 83 in line therewith, and a single chain, 115, follows the path shown in FIG. 2 in mesh with these four sprockets, and is kept taut by a takeup sprocket 116 which is adjustably mounted on a takeup arm (not shown) attached to the adjacent feeder side frame 119. Since shaft 20 is driven as previously described, the sprocket on shaft 20 acts as a driving sprocket and drives the chain 115 in the direction shown, and this chain 115 in turn drives the other four sprockets so that the pullout rollers 70 and the upper tape roller 83 are all driven in the directions shown. As previously indicated, roller 150 drives the lower sample conveyor tapes 45 and roller 83 drives the upper sample conveyor tapes 44.

SAMPLE PICKUP AND TRANSFER

Stop fingers 39 are mounted on shaft 85 which is journaled in conveyor side frames 79. Shaft 85 is so positioned that when the stop fingers 39 are in the down, or full line, position as shown in FIG. 2, they will stop a sample being carried by upper and lower conveyor tapes 44 and 45 with its leading edge somewhat beyond the point of tangency between the circumference 151, previously described, of sample transfer

wheel 35, and the plane of the lower surface of the upper conveyor tapes 44. The split cams 74 on shaft 19 actuate linkage 145, which rocks shaft 85 so that stop fingers 39 are moved from the full-line position to the dotted line position shown, and returned to the full-line position, once for each revolution of shaft 19. Shaft 19 is in turn positively driven by sprockets and chains, as will be more fully described hereafter, so that it completes one revolution for each sample fed by the sample feeder 90. Since cams 74 are a pair of split cams they may be individually adjusted, one to control the time at which the stop fingers 39 move from the full-line position to the dotted line position, and the other to control the time at which the stop fingers 39 return from the dotted line position to the full-line position.

The sample separating and feeding device of the sample feeder 90, such as the shuttle arrangement previously described, is timed so that a sample will be delivered to the bite of the pullout roller 70 and in turn delivered by them onto the sample conveyor 40 between the lower conveyor tapes 45 and the upper conveyor tape 44, and conveyed by these tapes so that the leading edge of the sample comes in contact with, and is stopped by, the stop fingers 39 just after the stop fingers have returned to the full-line position. The stop fingers 39 may be adjustably positioned at any point across the width of the stop finger supporting shaft 85, and generally one or more pairs of the stop fingers are used for each sample transfer wheel 35, with the stop fingers of each pair being positioned on opposite sides of the upper conveyor tape 44, generally in line with the lower conveyor tapes 45, and out of the path followed by the suction heads 38 carried by the sample transfer wheel 35.

The timing is such that as a sample is stopped by the stop fingers 39 and held in position on the conveyor, one of the suction heads 38 carried by the sample transfer wheel 35 is approaching the point of tangency between the circumference 151 of the sample transfer wheel 35 and the plane of the lower surface of the upper conveyor tapes. At the time that the suction head 38 comes in line with this point of tangency, suction is drawn in the suction head, by means which will be described hereafter, so that the bottom surface of the sample is seized by the suction head. At this same instant the stop fingers 39 are rocked from the solid line position into the dotted line position so that the sample is free to be carried around the circumference 151 by the suction head 38.

As previously described, just at the time that the leading edge of a sample reaches the stop fingers 39, the carrier sheet detector 42 on the main conveyor detects for the presence or absence of a carrier sheet, and if a carrier sheet is detected to be present the sample reject stripper fingers 46 remain in their raised position, as shown in FIG. 1, and the sample is carried around by the suction head 38 to the point where it is affixed to the carrier sheet. However, if the detector 42 detects that no carrier sheet is present, then the sample reject stripper fingers 46 are moved down into the reject position shown in FIG. 2, and as the suction head 38 passes this position it passes between a pair of the sample reject stripper fingers 46, but the sample carried by the suction head 38 is stripped therefrom by the stripper fingers 46 and delivered out onto the endless tape 87 of the cross-conveyor. The endless tape 87 of the cross-conveyor extends across the width of the machine, over cross-conveyor tape rollers 86 at either side of the machine, one of which is driven by a chain and sprocket drive 89 from a separate motor 88, so that samples thus stripped off onto the cross-conveyor are delivered into a reject hopper (not shown) at the side of the machine.

Since each sample is turned over as it is carried, by one of the suction heads 38 on the sample transfer wheel 35, from the point where it is picked up from the sample conveyor 40 to the point where it is affixed to a carrier sheet, it therefore follows that the samples must be loaded into the magazine 43 of the sample feeder 90 with their "face" down and their "bottom" surface on top. The "bottom" surface of the samples refers to that surface of the sample which will be adhered to a carrier

sheet when the sample is affixed thereto and the "face" of a sample is that surface of the sample which will be on top, and which will be visible, after the sample has been affixed to a carrier sheet. A sample which has been separated and conveyed to the stop fingers 39, as previously described, will therefore be picked up by one of the suction heads 38 with its "face" against the section head and its "bottom" surface will be the outer surface as it is carried by the section head 38 around the perimeter 151 of the sample transfer wheel 35.

10 The radial distance from the "bottom" surface of a sample (which is uppermost as the sample lies, "face" down in the pickup position on the conveyor 40 with its leading edge in contact with the stop fingers 39) to the center of the sample transfer wheel 35, along a radial line perpendicular to the surface of the sample, is equal to the radius of circle 151, which is the circumferential path traveled by the point where this line meets the "bottom," or outer, surface of the sample as the sample is carried around by the suction head 38. The point of tangency between this circle 151 and the bottom surface of the upper conveyor belts 44, will be referred to as the pickup point, 153.

15 The point of tangency between this circle, 151, and the top surface of a carrier sheet being carried along the main conveyor 30, will be referred to as the affixing point, 154.

20 The bottom surface of the upper sample conveyor tapes 44 is maintained in a fixed plane spaced from the center of sample transfer wheel 35 by the radius of circle 151. Variations in thickness of different carrier sheets are accommodated by vertical adjustment of the platen roller 112, which supports the area of the carrier sheet to which a sample is to be affixed, from below, at the affixing point 154, so that the upper surface of the carrier sheet at this point lies in a plane tangent to circle 151 and also spaced from the center of sample transfer wheel 35 by the radius of circle 151. The sample is thus pressed onto the carrier sheet with just the proper pressure between the suction head 38 from above and the supporting platen roller 112 from below.

25 In order to accomplish this, the "bottom" surface of the sample (which is uppermost) must always lie in the same plane as the bottom surface of the upper sample conveyor tape 44, when the sample is in the pickup position with its leading edge in contact with the stop fingers 39, regardless of the thickness of the particular samples being handled. Since it is a feature of

30 the machine that it is capable of affixing samples of a wide range of materials, which vary widely in size and thickness, the following devices are supplied to accommodate a wide range of sample thicknesses: the upper surface of the lower sample conveyor tapes 45, supported as previously described, may be

35 raised or lowered to accommodate samples of varying thickness. By loosening the upper and lower lock nuts that hold I-bolts 147 in position, the entire lower sample conveyor, including frames 148, may be pivoted about the center of shaft 20, and then locked into position by retightening the upper

40 and lower lock nuts on I-bolts 147, with the lower conveyor frames 148 in the proper position so that a sample of any thickness, within the thickness range for which the particular machine is designed, may be held snugly between the upper conveyor tape 44 and the lower conveyor tapes 45, at the pickup position 153, with its "bottom," or uppermost, surface in the fixed plane of the bottom surface of upper sample conveyor tape 44.

45 At the point where the sample enters onto the sample conveyor, between rollers 150 and 83, the thickness of the sample is accommodated by adjustably swinging the mounting for shaft 82, which carries the upper driven conveyor tape roller 83, as previously described.

50 The radial distance from the "face" of a sample in the pickup position 153, to the center of the sample transfer wheel 35 will therefore vary, depending upon the thickness of the samples being affixed. In order to accomplish the proper pickup of the sample by one of the suction heads 38, it is important that the surface of the suction head 38 just contact the "face" of the sample as the suction head comes in line with the

pickup point 153. In order to accomplish this, the suction heads 38 are mounted on the sample transfer wheel 35 by means of a threaded stem 91, by means of which the outer curved surface of the suction head 38 may be positioned adjustably at varying distances from the center of the sample transfer wheel 35. When each suction head 38 has been thus properly adjusted to just contact the "face" of a sample in the pickup position 153 each suction head is then locked in this position by tightening the lock nut 155 on the threaded stem 91. The outer (or "bottom") surface of the sample will then remain in the path of circle 151 as the sample is carried around the affixing position 154.

TWO-STREAM OPERATION

The description thus far has dealt with the case in which a single stream of carrier sheets is fed by the carrier sheet feeder 29, and a single stream of samples is fed by the sample feeder 90, and affixed thereto. The machine is designed, however, so that two or more streams of samples may be fed by the sample feeder 90 and affixed to a single stream of carrier sheets fed by the carrier sheet feeder 29, and alternatively more than a single stream of carrier sheets may be fed by the carrier sheet feeder 29 and in turn one stream of samples, or more than one stream of samples, may be fed for each stream of carrier sheets. For each additional stream of carrier sheets to be fed by the carrier sheet feeder 29, additional magazines, separating means, pullout rollers and conveying means, all as previously described, are provided across the width of the machine in side by side relationship; and similarly, for each additional stream of samples to be fed by the sample feeder 90, additional magazines, separator mechanism, pullout rollers, conveying means, stop fingers and sample transfer wheels are provided in side by side relationship across the width of the machine. FIG. 2A illustrates a cross section, taken along line 2A—2A of FIG. 2, of the sample conveyor means 40 and the cooperating sample transfer wheels 35, for two streams of samples, which may then be affixed either to a single stream of carrier sheets or to two streams of carrier sheets.

When only a single stream of carrier sheets is being handled with a single stream of sample being affixed thereto, the operation of the detector 42 to detect for the presence or absence of a carrier sheet is as previously described, and no detector is required to determine whether a sample is present or not at the pickup position 153, since in the absence of such a sample no purpose would be served in having the sample reject fingers 46 move into the down, or reject, position. However, whenever more than a single stream of samples is being affixed, either to a single stream of carriers or to more than a single stream of carriers, then a carrier sheet detector 42 is positioned in each stream of carrier sheets, along the main conveyor 30, and, in addition, a sample detector 75 is positioned as shown in FIG. 2, in each stream of samples to sense for the presence or absence of a sample at the pickup point 153 at exactly the same time that the detector or detectors 42 are sensing for the presence or absence of a carrier sheet or sheets on the main conveyor 30. In this case the circuits from these detectors are wired, in a manner which will be illustrated and described in connection with FIG. 15, so that if a carrier sheet is not present in *each* stream of carrier sheets being fed and if a sample is not present in *each* stream of samples being fed, then the absence of *any* carrier or *any* sample will cause the solenoid 36 to be actuated, and this in turn, through linkage 37, will cause the sample reject stripping fingers 46 to be moved into the down, or reject, position, and in this position any samples which are present in any stream, and are picked up by the appropriate suction head 38, will be stripped therefrom by the reject fingers 46 and delivered out onto the cross-conveyor tape 87, by means of which they will be delivered across the machine into the reject hopper (not shown) at the side of the machine.

ALTERNATE SAMPLE-REGISTERING MEANS

Instead of the stop fingers 39 and associated linkage 145, and actuating cams 74, an alternate means, shown diagrammatically in FIG. 2B, may be used for bringing the samples to the pickup position 153 in register with the suction heads 38. In this case, a timing belt 295 is substituted for the upper conveyor tape 44, with timing belt sprockets 296, 297 and 298 replacing the tape driving roller 83, the idling tape roller 146 and the tape tightener rod 95 respectively. The length of this timing belt is an exact multiple of one-quarter of the circumference of circle 151, and the outer flat surface of this timing belt carries rubber lugs 299 vulcanized thereto, and projecting from the outer flat surface thereof, and spaced apart by a distance exactly equal to one-quarter of the circumference of circle 151. This timing belt is driven at a speed such that its outer flat surface, and the lugs 299 carried thereon, move at exactly the same surface speed as the surface speed of circle 151. Lower conveyor tapes 45 are driven at a somewhat slower speed. The separating mechanism of the sample feeder 90 is timed so that a sample is delivered into the bite of the upper and lower pullout rolls 70 and by them onto the sample conveyor 40 so that the sample is delivered between lower tapes 45 and the flat surface of timing belt 295 and positioned between two of the lugs 299, projecting downwardly from the flat surface of the timing belt 295. The faster speed of the timing belt 295 causes the following lug 299 to catch up with the trailing edge of the sample and thereafter to push against the trailing edge of the sample and move it at the speed of the lugs 299. The lugs 299 are so positioned and driven with respect to the suction heads 38 on the sample transfer wheel 35 that when the sample reaches the pickup position 153 it is in register with one of the suction heads 38, and traveling at the same speed as the suction head. At this point, as described before, suction would be drawn in the suction head 38 whereby the sample would be seized by the suction head and thereafter carried with it through the curvilinear path of circle 151.

Alternatively, a similar result could be achieved by driving the lower conveyor tapes 145 at a speed in excess of the speed of the lugs 299 carried by the timing belt 295, in which case the sample would be carried ahead at a faster rate than the speed of the lugs until the leading edge of the sample contacted the lug ahead, and the sample would thereafter be conveyed at the speed of the lug until it reached the pickup point 153 in register with one of the suction heads 38, at which time the sample would be seized by the suction being drawn at that instant in the suction head 38, which would thereafter carry it around the curvilinear path of circle 151.

TRANSFER WHEEL AND ROTATING SUCTION HEADS

Referring specifically to FIGS. 2, 2A, 3, 4 and 5, the sample transfer wheel (or wheels) comprises a disc-shaped member 35, supported on and turning with shaft 13 which is journaled in the main frames 28, and having four suction heads 38, spaced 90° apart, secured thereto at its periphery. Desirably, suction heads 38 are threadably secured on disc-shaped member 35 by threaded nipple connection 91 so as to allow for adjustability of the suction heads 38 with respect to the surface of the "face" of a sample to be picked up at the pickup point 153. One of rotating disc member 35 is held against a flat stationary member 92 which has a partially disc-shaped portion which surrounds shaft 13 and is journaled on a rotating hub 300 projecting from the rotating disc-shaped member 35. Member 92 also includes a rectangular-shaped portion which projects towards the delivery end of the machine 26 and terminates in upper and lower arms which project above and below, and are supported by, a stationary sleeve 94 which surrounds shaft 14. The abutting surfaces of rotating disc 35 and the adjacent stationary member 92 are flat and are lapped together to provide close, uniform contact between these two surfaces. Preferably rotating disc 35 is made out of steel and adjacent stationary member 92 is made out of case iron, or the two are made out of other dissimilar metals to provide a good

bearing surface between them. There are four annular grooves 92a, 92b, 92c and 92d, in the face of the disc-shaped portion of member 92 which abuts the face of revolving disc member 35. Each of the suction heads 38a, 38b, 38c, and 38d has a radial passage, 35a, 35b, 35c and 35d, respectively which extends therethrough and radially through disc 35 to a point opposite the corresponding groove 92a, 92b, 92c and 92d, respectively, in the disc-shaped portion of member 92, and in each case the inner end of this radial passage connects with another passage 35a', 35b', 35c' and 35d', respectively, which extends at right angles therefrom to the face of rotating disc 35 which abuts member 92, and each of these right-angle passages 35a', 35b', 35c' and 35d' terminates in an opening which is in line with, and communicates with, the corresponding groove 92a, 92b, 92c and 92d, respectively, in the abutting disc-shaped portion of member 92. In member 92 there are four longitudinal passages a, b, c and d, two of which originate in each of the arms of member 92 which extend above and below the sleeve 94, surrounding shaft 14. Each of these passages is drilled to a depth such that its terminus is just opposite the corresponding groove in the face of the disc-shaped portion of member 92, and a right angle passage a', b', c' and d', respectively, connects each terminus with the corresponding groove 92a, 92b, 92c and 92d, respectively. Thus as the disc-shaped member 35 revolves, the passage through suction head 38a is at all times open to the groove 92a in the face of the disc-shaped portion of member 92, and through it to the outer terminus 92a' of the passage a, at the end of member 92 toward the delivery end of the machine, and with no other passage. Similarly, the opening in suction head 38b is continually in communication with the outlet 92b' of the passage b, at the end of member 92 toward the delivery end of the machine, and with no other passage, etc. A steel washer 301 and two resilient O-rings 302, held in place by a nut 303, at the outer end of the hub 300 of member 35, act to hold the two adjacent faces of rotating member 35 and stationary member 92 in close contact with each other. This contact is further aided by the atmospheric pressure operating against the outer faces of both rotating member 35 and stationary member 92 when a vacuum is drawn in one or more of the annular grooves 92a, 92b, 92c and 92d in the face of the disc-shaped portion of member 92.

Situated somewhat farther toward the delivery end of the machine and extending across the width of the machine between the side frames 28 is a square manifold member 103. Across the width of this manifold 103 there are a series of funnel-shaped holes extending from the top through the bottom, with four such holes being provided for each sample transfer wheel 35 that is to be used on the machine. Connecting with each of these funnel-shaped holes there is another passage, at right angles to the funnel-shaped hole, and leading from it to an opening in the forward face of the manifold 103, and together these each form a T-shaped passage, 103a, 103b, 103c and 103d, respectively, through the manifold 103. FIGS. 4 and 5 illustrate four of these T-shaped openings through the manifold, labeled 103a, 103b, 103c and 103d. A flexible hose 102a, 102b, 102c and 102d, respectively, of rubber or other similar material, connects the opening of each of these passages, which is at the forward side of the manifold, with the corresponding opening 92a', 92b', 92c' and 92d', respectively, at the ends of stationary member 92. These flexible hoses, 102a, 102b, 102c and 102d, allow the sample transfer wheel 35 and its associated stationary member 92 to be adjusted from side to side across the machine while still maintaining the connections to the ports in the manifold 103. Individual hoses 97 in turn lead from each of the openings of these passages which are in the bottom of the manifold 103 to individual suction pumps (not shown). Each of these separate and individual suction pumps operates continually during the operation of the machine and pulls a vacuum through each hose 97 at the bottom of each of the funnel-shaped openings 103a, 103b, 103c and 103d, respectively, in the manifold 103. Each of the openings in the top of the manifold 103 forms a valve 104

which is covered and sealed by a valve cover, having a resilient disc 158 on its face, and mounted at one end of a right-angle valve arm 225, which is individually pivoted on a rod 156, which extends across the width of the machine and is additionally supported by arms extending out from the manifold 103. The other end of the right-angle valve arm 225 carries a cam follower roller 157. These valves, as shown in FIG. 5, are similarly labeled 104a, 104b, 104c and 104d to associate them with the respective passages through the manifold 103, stationary member 92, and rotating member 35 with which they are associated. Adjacent to the position of the cam followers 157 there is a cam shaft 15, which extends across the width of the machine, and is journaled in the side frames 28 and driven through positive means so that it makes one complete revolution for each revolution of the sample transfer wheel 35. Located across this cam shaft, 15, are individual pairs of split cams 105, one pair being provided for each cam follower roller 157. These pairs of split cams are similarly labeled 105a, 105b, 105c and 105d as are the associated cam followers labeled 157a, 157b, 157c and 157d in FIG. 5 to identify them with respect to the valves with which they are associated. For example, when the raised portion of the cams 105d contact the cam follower roller 157d, the valve sealing member 158 of valve 104d is lifted and allows air to enter through the large top opening of the funnel-shaped hole 103d in the manifold 103. When the cams 105d revolve to the position in which the low portion of the cams is opposite, the cam follower roller 157d (as seen in FIG. 4), the resilient valve sealing member 158 of valve 104d drops onto the top of the funnel-shaped hole 103d and seals the opening from the outside atmosphere. Each cam in each pair is individually adjustable and therefore one of the two split cams may be used to determine the time in the cycle at which the valve is opened, and the other to determine the time in the cycle at which the valve is closed. The tendency of the valve to close by the force of gravity, when the high portion of the cam does not act on roller 157 to lift it off the face of the manifold, can be assisted by a spring (not shown) if desired.

It will thus be apparent that by adjusting the appropriate split cams each of the valves can be closed and opened at the proper time in the cycle so that each valve in turn is closed, and suction is drawn in each of the four suction heads, 38a, 38b, 38c and 38d. When each reaches the pickup point 153, as the sample transfer wheel 35 rotates, and this suction is then maintained so that the sample is carried by the suction head, around to the affixing point 154, at which point the opening of the appropriate valve breaks the suction and releases the sample.

If the sample reject stripping fingers 46 are in the down or reject, position they will act to strip the sample from the suction head 38, notwithstanding the fact that suction continues to be drawn through the suction head. Since each suction head is independently served by a separate suction pump and controlled by separate valve mechanism, each suction head acts independently to pick a sample up at the pickup point 153 and to release it at the affixing point 154 and the strength of the suction available for this purpose at each suction head is unaffected by whether or not a sample is being carried by one of the other suction heads.

GLUE APPLICATION

Referring now to FIGS. 1, 2 and 3, a photocell 108 and a light source 107 are mounted in a holder 159 in such a manner that the beam from the light source is directed at the lens of the photocell. The holder 159 may be mounted anywhere across the width of the machine on spreader bar 161, which extends between the main frames 28 of the machine proper. The holder 159 may be positioned as close to one side of a sample transfer wheel 35 as it may be, without actually contacting any part of the sample transfer wheel 35 or the suction heads 38 carried thereby. In this position, as best seen in FIG. 3, a sample 41, carried by one of the suction heads 38, will

pass through the beam from light 107 as the sample is carried past the position of the holder 159, thereby momentarily interrupting the light beam and preventing it reaching the lens of the photocell 108.

One or more hot-melt glue guns 109 are mounted horizontally in position to fire one or more streams, or beads, of hot glue horizontally onto the outer or "bottom" surface of a passing sample carried by one of the suction heads 38. Each glue gun is mounted on two shafts 111 which extend across the width of the machine and the position of the glue gun may be adjusted from side to side across the machine along shafts 111. The shafts 111 are in turn supported at either end in a framework which slides along a longitudinal support bar 110 attached to each main frame 28. By sliding the entire glue-gun-supporting mechanism along the longitudinal support bars 110 the distance from the nozzle of the glue gun to the bottom surface of a sample being carried along circle 151 may be adjusted. The glue gun, or guns, 109 are connected to the main hot melt unit 34 by heated flexible hoses 160, through which a continuous flow of hot glue is constantly circulated, to and from the glue guns 109, and maintained under hydraulic pressure. When a solenoid-operated air valve in the glue gun is actuated, the valve in the glue gun is opened and the hydraulic pressure causes a stream of hot glue to be shot horizontally from the nozzle of the glue gun, through each orifice in the nozzle, and this stream of hot glue is cut off when the valve is closed. Commercially available, adjustable control means (not shown) control the timing of the opening and closing of the solenoid actuated air valve and thereby control the time at which the stream of hot glue starts firing and the time at which it is cut off. The control means are actuated when the light beam 107, directed at the photocell 108, is interrupted by the passage of a sample therethrough, and the control means are adjustable to that, depending upon the speed of the machine, the stream of glue will start firing a predetermined number of milliseconds later, corresponding to the time required for the sample to pass from the position where it first breaks the light beam to a position in line with the stream of glue fired by the glue gun, and the stream of glue will then be fired for a predetermined number of milliseconds, also related to the speed of the machine, and also adjustable to control the length of the glue bead applied to the "bottom" surface of a sample. It is thus possible to apply a glue bead or beads to the "bottom" surface of each sample, with the glue beads being of any desired length, and positioned at any desired place or places on the outer or "bottom" surface of a sample.

Since the solenoid-operated air valve controlling the firing of the glue gun is actuated only by the passage of a sample through the light beam, it is clear that no glue will be fired when no sample is present, irrespective of whether the absence of a sample was caused by the failure of the sample feeder 90 to feed the sample or by the removal of a sample from a suction head 38 by the sample reject stripper fingers 46, prior to the time that the suction head 38 passes the position of the light beam.

While a particular structure for the application of hot melt glue to the bottom surface of the samples has been illustrated and described it will be apparent to those skilled in the art that a number of equivalent arrangements could be used alternatively, such as the similar application of a cold adhesive through a pressure gun applicator, or the application of adhesive to the outer or "bottom" surface of the samples by means of applicator rolls or cams, with the glue being supplied and metered to the surface of these rolls or cams from a glue trough of known design. Also, alternatively, the glue or adhesive may be applied at the appropriate position on the surface of a carrier sheet to which a sample is to be affixed, and in this instance similar control means would be utilized to prevent the application of adhesive to the carrier sheet in the absence of either a sample or a carrier sheet.

When more than a single stream of sample is being applied, separate photocells 108 and a separate control means for the solenoid-actuated air valves in the glue guns 109 are provided

for each sample stream so that no glue will be fired in a particular stream unless the light beam to the photocell is interrupted in that stream. This insures that no glue will be fired in a stream in which no sample is present even though a sample may be present in an adjoining stream or streams.

When a sample, with adhesive applied to its outer or "bottom" surface, reaches the affixing point 154 its outer surface, as previously described, is travelling at exactly the same surface speed as the corresponding carrier sheet, and the sample is pressed against the carrier sheet, as the sample and carrier sheet together are squeezed between the face of the suction head 38, above, and the supporting platen 112 below. This causes the adhesive to affix the sample to the carrier sheet, and at this instant the suction, which has been holding the sample to the suction head 38, is broken by the action of the suction valve mechanism 104 previously described, so that the suction head proceeds on around the circular path of the sample transfer wheel 35 back to the position 153 where it will pick up another sample, and the sample is carried on by the carrier sheet to which it has been affixed. As has previously been described, the vertical position of the platen 112 is adjustable to accommodate different thicknesses of carrier sheets and to apply the desired degree of pressure or squeeze to the sample and carrier sheet.

As the sample and carrier sheet pass on through the machine to the delivery end of the machine they may, if desired, pass between upper and lower squeeze belts, 320 and 313, respectively, as shown diagrammatically in FIG. 19, both of which move at the same surface speed as the carrier sheet and which act to hold the sample in position on the carrier sheet and to maintain pressure between the sample and the carrier sheet for a more extended period of time, during which time the adhesive becomes more firmly set. Such squeeze belts, when used, are adjustable from side to side so that they may be aligned with the position of the glue bead or beads, and they are also adjustable vertically to allow for adjustment of the pressure, or squeeze, which they exert on the combined carrier sheet and affixed sample.

In any case, the carrier sheet, after it has passed the affixing point 154, moves on through the machine and passes under the detector 48, in line with the lateral position at which a sample should be affixed. At the time when the front to back position on the carrier sheet, at which the sample should be affixed, passes under the detector 48, the detector is actuated to sense for the presence or absence of a sample. If the detector 48 senses that a sample is present, the reject fingers 49 remain in the down, or closed, position and the carrier sheet, together with the affixed sample, is carried over the reject fingers 49 by the ejector rollers 113 and 162 and associated mechanism and then out onto the delivery conveyor 294, which then carries them either onto the delivery mechanism of the machine, or into a folder 117 if the carrier sheets are thereafter to be folded. If, however, the detector 48 senses that a sample is not present at the position to which it should be affixed to the carrier sheet, the reject fingers 49 move up into the reject position and the ejector rolls 113 and associated mechanism then cause the carrier sheet to be driven against the bottom surface of the reject fingers 49, which deflect the sheet and cause it to be driven down onto the reject conveyor 114, which in turn delivers it into the reject hopper 50.

The completed carrier sheets, with samples affixed thereto, (either folder or unfolded as the case may be) are finally delivered by a delivery device of known design, such as a creeper tape delivery onto which the completed carrier sheets are delivered in overlapped relationship so that they may be scooped up and jogged and placed in cartons or other containers for shipment or subsequent operations.

SPECIFICS OF THE SHUTTLE FEEDER MECHANISM

An important and unique feature of the automatic sample-affixing machine described herein is its versatility, in that it has the inherent capability of separating and feeding a wide

range of "samples," which may vary widely in thickness, length, width and character, and affix these to an equally wide range of carrier sheets which may also vary widely in thickness, length, width and character, as previously described in some detail. To accomplish this the automatic affixing machine is basically constructed in a way that allows feeders of different types to be used interchangeably for the feeding of carrier sheets, and similarly allows feeders of different types to be used interchangeably for the feeding of samples.

In addition, the use of the Anderson et al. feeders, referred to hereinabove, provides a range of flexibility in and of itself since these feeders are themselves designed to provide for the alternate use of either a continuous load friction feeder, separating mechanism or a shuttle-type feeding and separating mechanism. It has been found that while certain relatively thick and stiff samples such as single, packaged razor blades for instance, may be successfully handled by the standard mechanical shuttle mechanism described in the Anderson et al. patents referred to hereinabove, certain important modifications of this shuttle arrangement are required to successfully separate and feed certain other types of samples. One class of materials that are widely encountered as "samples" to be affixed to carrier sheets are what are referred to as "packettes." A "packette" is a small, relatively flat container, containing a relatively small sample of a product sealed therein, and generally formed by placing the sample of the product between two sheets of material, such as aluminum foil, of approximately equal size and fastening the two sheets of material together to form an enclosure around the product by sealing the four edges of the two sheets of material to each other. The two sheets of material forming the packette may be metal foil, metal foils laminated to plastic or with plastic coatings, or they may be sheets of plastic which may be clear, translucent or opaque and which in turn may be coated with or laminated to a metallized surface. The edges of the packette may be heat sealed, may be sealed with an adhesive or may be sealed by crimping or a combination of these methods may be used. At least one surface of the packette is commonly printed upon to identify the product which is enclosed within the packette. Packettes are used to package samples of a wide variety of products, including such items as samples of fragrances such as perfumes and colognes, in which case the packette normally contains a small flat square of absorbent material, similar to a blotting paper, which has been saturated with the perfume, cologne or other fragrance. Packettes are also often used to package samples of food stuffs such as instant coffee or tea, condiments, peanut butter, jams, jellies, preserves, etc. and also for packaging samples of various cosmetic oils, creams, powders, etc.; they are also sometimes used to package a variety of small articles such as coins, and a wide variety of other items.

The successful separating and feeding of single packettes from a stack of packettes presents some very specialized problems. Because of the relative thickness of the packettes a comparatively small number may be loaded into a magazine or hopper of a given size at one time, and it is therefore important that the feeding device employed be of a type that can be loaded continually while the machine continues to run, thus eliminating the need for frequent stops for reloading.

Attempts to feed packettes with shuttle means that depend upon pushing a sheet by its trailing edge encounter the difficulty that the force required to slide a single packette out from the bottom of a stack of packettes, held in a magazine, tends to bend or crumple the thinner, trailing edge of the packette, and in addition many packettes are received with some of their edges bent upward and some bent downward and, since most of them are made of materials that do not have a "memory," their edges retain these bent configurations with the result that the trailing edge of the bottom packette in the stack may be bent down, may be straight or may be bent up, but cannot be depended upon to be in a position to be contacted by a pusher member which would consistently contact the trailing edge of only the bottom packette in the stack but

not of the next packette above it. A further difficulty arises from the fact that if a shuttle feeder is set to push out the bottom packette of a stack of packettes, the gate, through which the bottom single packette is to be pushed, must be set to allow the passage of a single packette but not to allow the passage of more than a single packette. This means that the gate must allow the passage of the thicker body portion of the center section of the packette. However, if an opening of this size is left in the gate it will tend to allow the thinner leading edge portion of several packettes to enter the gate, and there will then be insufficient room for the passage of the body portion of the bottom packette. This can result in a jam-up, whereas to open the gate wider would invite the passage of more than a single packette, since the leading edges, like the trailing edges, may sometimes be straight and may sometimes be bent down and other times bent up and this will result in the leading edge of several packettes entering the gate together on some occasions whereas in other cases the leading edge of only a single packette will enter, and in some cases the leading edge of two packettes will enter and the wider opening in the gate may then allow the passage of two packettes instead of one.

Another complication arises from the fact that while in some cases the material enclosed within the packette is of uniform size and thickness, and is of such length and width that it very nearly fills the cavity within the packette, in other cases the material contained within the packette is fluid in nature and not necessarily uniformly distributed within the cavities of the numerous packettes involved. In still other cases, while the material enclosed within the packette may be of uniform length, width and thickness it may be considerably smaller than the cavity within the packette, and such materials will tend to be in different locations within the cavities of different packettes. The result of these varying circumstances is that whereas some packettes may tend to form a uniform stack within the feeder magazine, others tend to tip one way or the other and this tipping is constantly varying and changing, as different loads of packettes are loaded into the magazine of the feeder, with the result that an almost infinite number of combinations are encountered with respect to the relative thickness of different portions of the packette in a series of packettes.

An important element of this invention involves the shuttle feeder configurations that have been developed to successfully handle the separating and feeding of single packettes, notwithstanding the difficulties and problems outlined above.

Referring to FIGS. 6 through 11 inclusive, and to FIG. 2, the packettes are loaded, face down, into the sample magazine 43, where they are held in position by front guide 120 and side and back guides 68. The face of the bottom packette normally rests on the suction shuttle blade 67. The suction shuttle blade 67 is secured to and carried by the shuttle block 152, which is adjustably secured to the shuttle slide rod 72 which reciprocates longitudinally in bearing blocks at either end of the shuttle frames 77. The reciprocating action of shuttle side rod 72 originates in a crank arm at one end of shaft 12, and is transmitted to the shuttle slide rod 72 by means of linkage 73. There is an insert 137 in the face of the shuttle suction blade 67, and this insert is made of a polymer which has a very high coefficient of friction and excellent wearing qualities. There are suction slots 121 which extend across a major portion of the width of the suction shuttle blade 67 and extend through the polymer insert 137 and into the body of the steel suction shuttle blade 67 where they connect with a passage or passages which extend through most of the length of the suction shuttle blade 67 and in turn communicate with a similar passage through the shuttle block 152, and thence through an elbow nipple fitting to a flexible hose 71, which leads first to a valve similar to that described and illustrated in FIGS. 4 and 5 (or to a solenoid actuated valve), and then to a separate vacuum pump which draws a vacuum through the passages just described whenever the valve is closed so that the passages are not open to the atmosphere. The cams con-

trolling the valve are set so that suction is drawn at the slots 121 at the point where the suction shuttle blade 67 reaches the back end of its reciprocating stroke, and this suction is maintained in the slots 121 until the suction shuttle blade 67 reaches the point in its forward reciprocating stroke where the leading edge of a sample being carried forward by the blade 67 is seized by the bite of the pullout rollers 70, at which point the suction is cut off. The forward position of the suction shuttle blade 67 is considerably narrower than the narrowest packettes to be handled, and at the forward end of its reciprocating stroke it extends out over the shaft 101 of the lower pair of pullout rollers 70. The lower pullout rolls 70 are adjusted on the shaft 101 which carries them so that their inner side face, in each case, just clears the adjacent side of the suction shuttle blade 67, in its forward position. The upper surface of the suction shuttle blade 67 lies in a plane approximately tangent to the surface of the lower pullout rolls 70 and the bottom surface of the suction shuttle blade 67 clears the shaft 101 for the lower pullout rolls 70 when the shuttle blade is in its forward position. The upper pullout rolls 70, to complete each pair of upper and lower pullout rollers, are aligned directly above the respective lower pullout rollers.

The gate 69 is formed at the lower end of the forward magazine guide 120. There is a slot, or trough, 128 in the front face of the forward magazine guide 120, and at the bottom thereof. A flexible polymer strip 135 and a spring steel backup plate 136 fit snugly in the trough 128 and project below the bottom of the forward magazine guide 120, with the flexible polymer strip 135 being on the inside, or closest to the packettes, and extending farthest below the bottom of the front magazine guide 120. The spring steel backup plate 136 is on the outside of the polymer strip 135 and also projects beyond the bottom of the front magazine guide 120, but not as far as the polymer strip 135. A cross piece 130 extends across the front face of the forward magazine guide 120 and is secured thereto by screws 131 on either side of the trough 128. A similar crosspiece 176 bridges the trough on the forward face of the front magazine guide 120, at the very bottom thereof, and is brazed or spot welded in place on either side of the trough 128. The trough 128 is deepest at the bottom and tapers, and finally curves, and comes flush with the front surface of the forward magazine guide 120 at the top. Both the polymer strip 135 and a backup plate 136 fit snugly in the width of the trough and their thickness is such that they both fit snugly in the trough behind the cross member 176, at the bottom of the front magazine guide 120. The spring steel backup plate 136 passes outside and in front of the cross member 130, and is secured thereto by a screw 134 which passes through a slot in the backup plate 136, whereby the backup plate may be adjustably positioned to extend a greater or lesser amount below the bottom of the front magazine guide 120. At the point where the cross member 130 bridges the trough 128 the depth of the trough is somewhat less than the thickness of the polymer strip 135, so that when the screws 131 are tightened to draw the cross member 130 against the forward face of the front magazine guide 120 the cross plate 130 acts to grip and hold the polymer strip 135. It is thus possible to adjust the amount by which the polymer strip 135 projects below the bottom of the front magazine guide 120, independently of the adjustment for the backup plate 136. In addition to these adjustments the entire front magazine guide 120 is fastened to a cross member which extends in front of it across the width of the sample feeder 90, and is fastened to and forms a spreader bar for the main frames 119 of the sample feeder 90. The means (not shown) by which the front magazine guide 120 is affixed to this cross member of the feeder 90 allows the front magazine guide 120 to be adjustably positioned at any point across the width of the feeder, and also provides adjustable, micrometer screw means by which the entire front magazine guide 120 may be moved up or down, to provide micrometer adjustment of the opening in the gate, between the bottom surface of the polymer strip 135 and the top surface of the suction shuttle blade 67.

A "lifter" mechanism 76 lifts the stack of packettes in the magazine 43 during the backward stroke of the suction shuttle blade 67. This lifts the "face" of the bottom packette in the stack out of contact with the face of the suction shuttle plate 67 on its backward stroke, thus preventing the polymer insert 137, with its high coefficient of friction, from contacting the "face" of the bottom packette in the stack and drawing it back away from the gate. The lifter mechanism comprises two parallel fingers 163 which project along either side of the suction shuttle blade 67, between it and the shuttle frames 77. The front end of the fingers 163 is just behind the gate, and they extend back beyond the farthest point reached by the back edge of the polymer insert 137 and/or the suction slots 121 on the backward stroke of the suction shuttle blade 67. The two fingers 163 are held together by an integral cross member which extends below the path of the suction shuttle blade 67 and above the shuttle slide rod 72. They are both supported on an arm which projects upwardly from a supporting lever 165, located on one side of the shuttle frame below one of the frame members 77, and pivoted on stud 169 which in turn is mounted in plate 168 which is fastened to the shuttle frame 77, above, and projects downwardly therefrom. Along the outer side of the lever arm 165 there is a plate 166 which carries a cam follower roller 167 projecting outwardly from its outer surface. The plate 166 is adjustably secured to the lever arm 165 in a manner which allows the position of the cam follower roller 167 to be adjusted up or down with respect to the lever arm 165. Directly below the cam follower roller 167 there is a cam shaft 23, which extends across the width of the feeder and is journaled in the side frames 119 on either side of the sample feeder 90. Cam shaft 23 is driven positively so that it makes one complete revolution for each complete forward and back reciprocating stroke of the shuttle slide rod 72. Fastened to cam shaft 23, and adjustably positioned across it so that they may be positioned directly below the cam follower roller 167, is a pair of split cams 78, the combined width of which is approximately equal to the width of the cam follower roller 167. The fingers 163 may thus move up and down pivoted about the center of the stud 169. The high part of the split cams 78, acting on the cam follower roller 167, acts to pivot the lever arm 165 upwardly about the center of the stud 169, and to lift the fingers 163. When the high part of the split cams 78 pass out from under the cam follower roll 167 the weight of the entire lifting mechanism, aided by return spring 164, causes the lever arm 165 to pivot downwardly about the center of stud 169, thus lowering the fingers 163. The vertical position of the cam follower roller 167 in relation to the split cams 78 is adjusted by means of the adjusting plate 166, to which it is mounted, so that the top surface of the fingers 163 are below the level of the top surface of suction shuttle plate 67 when the lifter fingers 163 are down, and so that the top surface of the lifter fingers 163 is above the top surface of the suction shuttle plate 67 when the lifter fingers are up. One of the split cams 78 is adjusted around cam shaft 23 so that the timing is such that the lifter fingers 163 move from their raised position to their lowered position just as the suction shuttle blade 67 reaches the back end of its stroke, which is also the instant at which suction is drawn in the slots 121. The lifter fingers 163 then remain in their lowered position as the suction shuttle blade 67 moves forward, carrying the bottom packette in the stack with it. The other cam in the pair of split lifter cams 78 is adjusted around cam shaft 23 so that the lifter fingers 163 are again lifted into their raised position just as the trailing edge of the packette passes the forward edge of the lifter fingers. The lifter fingers 163 then remain in the raised position, holding the face of the next bottom packette out of contact with the upper face of the suction shuttle blade 67 until the suction shuttle blade has reached the back end of its stroke, and the cycle is then repeated.

The overall operation of the suction shuttle feeder in feeding packettes one at a time is therefore as follows: The flexible polymer strip 135 of the gate 69 is spaced from the top surface 75 of the suction shuttle blade 67 by a distance just sufficient to

allow only the leading edge of a single packette to pass therethrough. The backup plate 136 is positioned in front of the polymer strip 135 at a position which allows the bottom edge of the polymer strip 135 to flex just enough to allow the body of only a single packette to pass through the gate between the flexed polymer strip 135 and the top surface of the suction shuttle blade 67. When the suction shuttle blade 67 is at the back end of its stroke the lifter fingers 163 move down, and the pack of packettes is lowered until the "face" of the bottom packette rests on the upper face of the suction shuttle blade 67, with the polymer insert 137 and the suction slots 121 centered laterally under the packette, toward the front of the body of the packette. At the same time suction is drawn through slots 121, drawing the "face" of the packette firmly into contact with the face of the polymer insert 137. Thus held, the high coefficient of friction of the surface of the polymer insert 137 causes the bottom packette to move forward with the suction shuttle blade 67 during its forward stroke. The thin leading edge of the packette first passes under the bottom edge of the polymer strip 135 in the gate 69, but the polymer strip 135 acts to hold back the leading edge of the packette or packettes above. As the body of the packette passes through gate 69 the polymer strip 135 is flexed to allow the thicker body portion of the packette to pass, but is restrained by the backup plate 136 sufficiently to prevent the packette above to pass through the gate. When the suction shuttle blade 67 has carried the packette forward to the point where the leading edge of the packette has been seized in the bite of the two pairs of upper and lower pullout rollers 70 on either side of the suction shuttle blade 67, the suction in the slots 121 is broken, causing the packette to be released from suction shuttle blade 67. The surface speed of the pullout rollers 70 is faster than the surface speed at which the packette was being carried by the suction shuttle blade 67 and the packette is therefore pulled out rapidly by the upper and lower pullout rollers 70 and delivered by them onto the sample conveyor 40. As soon as the trailing edge of the packette passes beyond the leading edge of the lifter fingers 163, the lifter fingers raise and lift the stack of packettes, thereby raising the face of the next bottom packette above the plane of the top surface of the suction shuttle blade 67. The face of the polymer insert 137 therefore does not contact the face of the next bottom packette as the suction shuttle blade 67 completes its backward stroke, and the next bottom packette is therefore not drawn back from the gate by the frictional action of the surface of the polymer insert 137, as would be the case were the packette not lifted out of contact by the lifter fingers 163. When the suction shuttle blade 67 reaches the back end of its stroke the lifter fingers 163 drop, dropping the pile of packettes, so that the next bottom packette lies in contact with the top surface of the suction shuttle blade 67, and the cycle is then repeated. The repeated lifting and dropping of the stack of packettes by the lifter fingers 163 performs the added function of agitating the stack of packettes in the magazine, so that the stack of packettes descends uniformly without getting stuck in the magazine as packettes are withdrawn from the bottom of the stack. The angle of the sample magazine 43, which is tipped forward 20° from the vertical, acts to keep the leading edges of the packettes in the magazine in contact with the forward magazine guide 120, and in addition it has been found helpful in some instances to employ both a flat spring and fixed back stop means (not shown) to hold the trailing edge of the packettes at the bottom of the stack in position.

In order to facilitate the loading of packettes into the sample magazine 43 as the machine runs, and at the same time provide proper side guides for the packettes in the magazine, the apparatus illustrated in FIG. 10 is used. The packettes are purchased and delivered to the machine packaged in long narrow cardboard cartons 174, each of which contains a single row of packettes, and may be opened at the end toward which the "face" of the packettes face.

FIG. 10 illustrates the manner in which packettes are loaded into the sample magazine 43 from such a carton 174. Long flexible strips 118 are mounted inside each of the magazine side guides 68. Each of these long flexible strips 118 is held at its bottom end, and at one or more points above its bottom end, by studs 127, which are firmly affixed both to the adjacent side guide 68 and the strip 118, and act to hold the strip 118 firmly at a fixed distance in front of side guide 68, over a distance extending from the position of the bottom stud 127, 10 which is located approximately in line with the top surface of the suction shuttle plate 67, and extending up to the position of the uppermost of the studs 127. From that point to the top of the side guides 68 the long flexible strips 118 are supported by a series of studs 171, each of which has a flat button-shaped portion securely fixed to the outer surface of the strip 118, a smaller shank portion, each of which projects through a hole 172 in the side guide 68, and a head portion which is round and flat and which is outside of the side guide 68 and is larger 15 than the hole 172 through the side guide 68. On the inner face of the side guide 68 each of these holes 172 is countersunk, about two-thirds of the way through the thickness of side guide 68, to a diameter somewhat larger than the diameter of the button-shaped portion of stud 171 which is affixed to the strip 118. In each case there is a spring 173 surrounding the button-shaped portion of the stud 171 whose inner diameter is such that it fits snugly around the button-shaped portion of stud 171, and whose outer diameter is such that it fits snugly 20 into the countersunk portion of hole 172. The length of the studs 171 is such that, when a box 174 is not inserted into the magazine between the strips 118 on opposite sides of the magazine, the springs 173 will cause the heads of the studs 171 to lie in contact with the outer surface of the side guides 68, and when in this position the upper portion of the long flexible 25 strips 118 will be held vertically in line with the lower portion of these strips, which is supported by the fixed studs 127. In use, the side guides 68 are positioned, for any particular packette, so that the sides of a stack of packettes will be guided by the inner faces of the long flexible strips 118 and, throughout the length of the strips 118, and particularly at the lower end of these strips 118, where they are supported by the studs 127, there will be clearance between the side edges of the packettes in the stack and the inner faces of the strips 118. The box 174 containing a single row of packettes is, of course, 30 wider than the packettes themselves, and when such a box is inserted into the magazine 43, between the flexible strips 118, the springs 173 will be compressed and the studs 171 will be pushed outwardly as the insertion of the box 174 moves the flexible strips 118 outwardly toward the side guides 68. In operation the end of the box toward which the packettes face is torn off, and the packettes are held in the box by placing a finger 175 over this end as the box is tipped up and the opened end inserted into the top of the magazine 43, between the flexible strips 118. This is done when the supply of the packettes, 35 41, in the magazine has dropped down enough so that the number of packettes contained in one box may be accommodated in the magazine, but before the supply already in the magazine has been exhausted. The box 174 is thus inserted into the magazine with a finger covering the opening in the bottom of the box, to hold the packettes therein as the box is inserted into the magazine. After the box 174 has been inserted part way into the magazine 43, the finger 175 is moved downwardly allowing the packettes above to follow it down, 40 out of the box, until the finger contacts the top of the uppermost packette 41 already in the magazine. The finger is then withdrawn and the packettes from the box, part of which are still in the box 174, now rest on the supply of packettes that were previously in the magazine. During this operation the flexible strips 118 form a funnel-shaped side guide from the bottom of the box down to the point where the strips 118 are supported by the fixed studs 127. The box is then withdrawn, 45 leaving the packettes which it contained in the magazine, and as the box 174 is withdrawn the flexible strips 118 move in, under the action of the springs 173, until the upper portion of 50 55 60 65 70 75

the strips 118 is in vertical alignment with the lower portion, as described previously, when the box has been completely withdrawn. The packettes are thus supported uniformly throughout the height of the magazine along their side edges, and even during the loading process the lower portion of the stack of packettes is thus guided and supported, and even the portion of the strips 118 between the bottom of the box and the top of the fixed studs 127 forms a funnel-shaped guide which will bring any packettes which fall to one side or the other into line between the lower portions of the flexible strips 118, as the packettes move downward in the stack, and, further, as the box is withdrawn all packettes in the stack will be properly aligned as previously described. Similar flexible guide strips 118, similarly supported, may be provided along the inside surface of back guides, which form an angle with each of the side guides 68 which are at the back of the magazine, thus providing similar support for the packettes from front to back, while the leading edges of the packettes in the magazine remain in contact with the front guide plate 120.

When packettes are encountered on which the leading edges are bent, sometimes up and sometimes down, feeding difficulties are encountered, and particularly so with respect to those packettes whose edges are bent up, since in this case the leading edge, instead of passing through the space left for it between the gate 69 and the suction shuttle blade 67, may instead jam against the face of the polymer strip 135 and be crumpled as the packette is moved forward, causing a jam-up and the cessation of feeding. Similarly, when the material encased within the packettes is of such a nature that it may shift from one position to another within a series of packettes, a similar situation may occur when a series of packettes is encountered in which the material therein has shifted toward the front of the packettes, thereby making them thicker at that point, with the result that their leading edges are raised and their trailing edges are lowered, as they rest in the stack in the feeder magazine 43. Under these circumstances a similar jam-up may be caused, in similar fashion, even through the leading edge of a packette may not actually be bent upwards, but is instead tipped up by the configuration of the material contained within the packettes. FIG. 11 illustrates means that have been developed to overcome either or both of these problems. As seen in FIG. 11, there is a series of tapped holes 178 along the top faces of the shuttle side frames 77. A pair of screws 177 with rounded or smoothed heads are inserted into a pair of these tapped holes 178 which are directly opposite each other in the two shuttle frame members 77, and positioned near the trailing edge of the packettes being handled. By screwing the screws 177 into the selected pair of tapped holes 178 a greater or lesser distance, the height of the heads of the screws 177 may be adjusted so that they lift the trailing edge of the packettes by the right amount to offset the tendency of certain packettes to rest with their trailing edges down and their leading edges up, as a result of the position of the material within the packette, making such packettes thicker toward their leading edge. This has the result of holding the leading edge of the packette either straight or tipped slightly downward, so that it will pass through the gate properly as previously described. Also shown in FIG. 11 is a member 138, which is the same width as the front magazine guide 120 and extends from the top of the front magazine guide 120 to near the bottom thereof. Member 138 is held in sliding contact with the front magazine guide 120 by means of two or more studs 170 whose shanks are fixed in the front magazine guide 120, and extend through vertical slots in member 138, and whose flat heads slide in recessed slots in the inner face of member 138 and thereby act to hold member 138 in sliding contact with the front magazine guide 120 as member 138 reciprocates vertically with respect to the fixed front magazine guide 120. Across the lower face of member 138 are a series of downwardly facing parallel ratchet teeth 139. A pair of split cams 141, mounted on "one-to-one" cam shaft 23 (which also carries the lifter cams 78), act through linkage 140 to slide member 138 up and down, with a reciprocating motion, along

the face of the front magazine guide 120. The packettes in the magazine rest with their leading edges against member 138, and the leading edges of the packettes toward the bottom of the stack catch under successive ones of the ratchet teeth 139, as they move toward the bottom of the stack. The up-and-down reciprocating motion imparted to member 138 is timed so that the ratchet teeth 139 move down as the packettes in the stack are lifted by the lifter fingers 163 of FIGS. 6 and 7, and the ratchet teeth 139 move up as the lifter fingers 163 move down. Thus the leading edges of successive packettes catch under successive ratchet teeth 139, and are actually ruffled and bent downwardly on each revolution of cam shaft 23. This insures that each packette will have its leading edge bent downwardly as it reaches the bottom of the stack, and also aids in assuring that the packettes tend to be tipped forward, rather than back, as they reach the bottom of the stack.

Another type of "sample" that is encountered consists of small squares of paper with microencapsulated fragrances coated thereon. These are small paper sheets which have previously been coated with a slurry which contains vast numbers of microscopic capsules with each of these tiny spherical capsules containing an infinitesimal amount of a fragrance sealed within it. When the surface of a sheet which has been coated with these tiny capsules, containing the fragrance, is scratched or abraded a number of the tiny capsules are broken and the fragrance is released.

It has been found that a different shuttle arrangement is necessary to successfully separate and feed single sheets, such as those coated with such microencapsulated fragrances. Referring to FIGS. 12, 13 and 14, a suction shuttle 124 is used which is made entirely of steel and has a concave, dished-out portion 133 along its upper surface extending from the leading edge of the suction shuttle blade 124 back past the last of the suction slots 121, and thereafter tapering up gradually to blend with the top surface of the suction shuttle blade. In this case the gate, 125, is formed by a steel insert member 129 which fits snugly in the groove 128 in the forward magazine guide 120 and is held in place therein by screw 134. The bottom portion of this steel insert 129, which projects below the bottom of the front magazine guide 120, is curved as seen at 132. The small squares of paper with a microencapsulated coating are loaded into the sample magazine 43, with the coated face down, and in this position the coated face of the bottom sheet rests on the upper surface of the suction shuttle blade 124.

The lifter mechanism of FIGS. 6 and 7 is used, as previously described, and performs the dual function of preventing the coated surface from being scratched on the backstroke of the suction shuttle blade 124 and also acts to agitate the stack of sheets in the magazine to keep them moving downward properly, as well as preventing any residual suction which may remain in the slots 121 from acting to pull the next bottom sheet back from the gate on the backstroke of suction shuttle blade 124. The devices illustrated and described in connection with FIG. 11 are not used in this case. When the suction shuttle blade 124 reaches the back of its reciprocating stroke, the lifter fingers 163 drop down and the bottom sheet rests on the face of the suction shuttle blade 124. Suction is drawn in the slots 121, and this causes the center portion of the bottom sheet to be bent down into contact with the dished-out portion 133 in the forward top face of the suction shuttle blade 124. The lower curved portion 132 of the steel insert 129 forming the gate 125 projects downwardly to, or preferably just below the level of the plane of the top of suction shuttle blade 124. However, when the bottom sheet of the stack has been drawn down by the suction in the slots 121, to follow the contour of the dished-out portion 133 at the top of the blade 124, the center portion of this bottom sheet is drawn below the curved surface 132 of the steel insert 129, whereas the next sheet above, which has not been drawn down by the suction, is retained behind the curved portion 132 of the steel insert 129. Thus, as the suction shuttle blade 124 moves forward, it carries the bottom sheet with it into the bite of the pullout rolls

70, as previously described, whereas the next sheet above is retained by the steel insert 129 forming the gate 125. The action in other respects is as previously described.

Either of the above-described modifications of the standard shuttle feeder of the Anderson et al. patents may also be used in connection with the carrier sheet feeder in cases where the nature of the carrier sheets makes this desirable. It has been found for instance that the modifications described in connection with FIGS. 12, 13 and 14 are particularly useful when the carrier sheets flap-extended envelopes. Flap-extended envelopes are normally handled with the folded edge of the envelope as the leading edge, and the extended flap as the trailing edge, and in addition to this suction shuttle arrangement of FIGS. 12, 13 and 14, it has been found desirable to support and lift the bottom of the stack at the trailing edge, under the center of the extended flap of the bottom envelope, by means of a smooth metal finger (not shown). This finger is adjustable up and down so that the thinner, extended-flap portion of the stack can be raised somewhat to compensate for the fact that the body portion of the envelopes in the stack is thicker, and thereby tending to flatten the top of the stack somewhat. This also has the effect of helping to keep the bottom envelope in the stack forward, in contact with the gate. In addition, with some types of envelopes, it has been found helpful to support the leading portion of the stack, under the body of the envelopes, on either side of the shuttle mechanism, with a rubber surfaced roller or belt at either side, and on which the body of the bottom envelopes rests; and which turns in a direction to urge the bottom envelope forward, to hold it snugly in contact with the gate until it is seized by the suction shuttle blade and carried through the gate.

When the material to be fed by the shuttle feeder (whether a sample or a carrier sheet) is of sufficient thickness, and sufficiently stiff and of uniform thickness, the suction shuttle blade is replaced by a mechanical shuttle pusher blade, which has a lip which projects upwardly and can be adjusted so that it will catch trailing edge of the bottom sheet in the stack and push it forward through the gate and into the bite of the pullout rollers, without catching or disturbing the next sheet above. In some cases a combination of this arrangement and a suction shuttle blade of the type 124 shown in FIGS. 12, 13 and 14 has been found to work best.

CONTROL CIRCUITRY

As previously described in connection with FIGS. 1 and 2, a sensing device 42 is located above the main carrier conveyor 30, at a distance from the affixing point 154 equal to the circumferential distance along circular path 151 from the pickup point 153 around to the affixing point 154. At the times when a carrier sheet should be in position on the carrier conveyor, below the sensing device 42, the sensing device 42 is actuated to sense for the presence or absence of a carrier sheet. If a carrier is present, the sample reject fingers 46, which form the sample reject gate, remain out of the path to be traversed by a sample carried by one of the suction heads 38 (in the position shown in FIG. 1), and the sample then being picked up by one of the suction heads 38 is carried on around to the affixing position 154. If, however, the sensing device 42 detects that there is no carrier sheet present at that time, the sample reject fingers 46, forming the sample reject gate, move into the reject position (as shown in FIG. 2) and the sample which is then being picked up by one of the suction heads 38 is stripped from the suction head 38 when it reaches the sample reject fingers 46, which then deliver the rejected sample out onto the conveyor tape 87 of the cross conveyor, which in turn delivers the rejected sample into the reject hopper at the side of the machine.

If more than a single stream of carrier sheets is being fed, a sensing device 42 is provided for each stream of carrier sheets and these are wired together, in a manner which will be more fully explained hereafter, so that unless a carrier sheet is present in each of the streams, at the proper time, the sample

reject fingers 46 are actuated to move into the reject position (as shown in FIG. 2) and the sample or samples present are stripped and rejected as would have been the case if no carrier sheet were present.

5 If only a single stream of carrier sheets and samples are being handled, the sample detector 75 is not used, since in the absence of a sample there would be no need to move the sample reject fingers 46 into the reject position, as shown in FIG. 2. However, whenever more than a single stream of samples 10 are being handled, whether in combination with one, or more than one, streams of carrier sheets, then sample detectors 75 are employed, one for each stream of samples being handled, and each of these detectors 75 is actuated, at the time when a sample should be in position on the sample conveyor to be 15 picked up by one of the suction heads 38, to detect for the presence or absence of a sample in that position and at that time in each sample stream. The sample detectors 75 are wired in relation to each other, and to the sample detector or 20 detectors 42, in such a manner that, if any one or more of the samples and/or any carrier sheet is found to be absent, the sample reject stripper fingers 46 move into the reject position, as shown in FIG. 2, and any samples that are present are then 25 rejected as previously described. Only if all samples and all carrier sheets that are supposed to be present are in fact detected to be present, at the proper place and proper time, do the sample reject fingers remain out of the path to be followed by the samples, as illustrated in FIG. 1. Since, as previously 30 described, the firing of each glue gun is controlled by the passage of a sample, carried by one of the suction heads 38, through the light beam directed by the light 107 at the photocell 108, no glue is therefore fired in the absence of any sample or any carrier sheet. As a further precaution, when 35 more than a single stream of samples are being handled, the photocells 108 for each sample stream may be wired in parallel so that the light beams to each of the photocells must be interrupted simultaneously in order to cause the glue guns to be fired.

Also, as previously described, there is another detector, or 40 detectors, 48 located above the path traversed by the carrier sheet or sheets after they pass the affixing point 154. There is a detector 48 located in line with the path to be traversed by each sample affixed to a carrier sheet or carrier sheets. The detector or detectors 48 are longitudinally adjustable toward 45 and away from the delivery end of the machine, so that they may be located above the position to be occupied by the sample or samples affixed to the carrier sheet or sheets when the leading edge of the carrier sheet or sheets is a selected, predetermined distance away from the reject gate 49, thus allowing 50 time for the reject gate 49 to move into or out of the reject position, in response to a signal from the detector 48, before the leading edge of the carrier sheet or sheets reaches the reject gate 49. If more than a single stream of samples is being 55 handled, and there is therefore more than a single detector 48, all of the detectors 48 are in alignment with each other. The detector 48 comprises a roller mounted at the shorter end of a pivoted arm, with the other longer end of the arm magnifying any lifting motion imparted to the roller to press against the 60 sensing tip of a microswitch. The pivot for the arm and the mounting for the microswitch are mounted together on a plate, which is in turn adjustable up and down by micrometer increments so that it may be adjusted in such a manner that a carrier sheet, supported in a fixed plane from below, will pass 65 beneath the roller without lifting the roller about the pivot arm, but a sample affixed to a carrier sheet will lift the roller, causing the arm to pivot and the longer end of the arm to actuate the microswitch. At the time when a sample affixed to a carrier sheet should be beneath the roller, the detector is actuated 70 to detect for the presence or absence of a sample, and if a sample is found to be present the reject gate 49 remains in the closed position and the carrier sheet, with the affixed sample, passes over the reject gate 49 and on into the delivery mechanism of the machine (or into a folding machine 117, if one is being used). If, on the other hand, the detector 48 sen-

ses that no sample is present, the reject gate 49 opens and deflects the carrier sheet onto the reject conveyor 114, which in turn carries it into the reject hopper 50. If more than a single stream of samples is being handled, and there are therefore a plurality of detectors 48, the reject gate 49 remains closed and passes the carrier sheets on to the delivery mechanism (or folder) only if a sample is found to be present in *each* sample stream, whereas if *any* sample is found to be missing the carrier sheet or sheets are deflected into the reject hopper 50, as previously described.

As a carrier sheet leaves the carrier conveyor 30 its leading edge is seized by the bite of a pair of first ejector rollers. The first lower ejector roller 113 is driven and the first upper ejector roller 219 is an idler roller resting thereon. If the reject gate 49 is in the open, or reject, position these rollers 113 and 219 drive the carrier sheet against the bottom surface of the reject fingers 49 and the carrier sheet is thus deflected and driven down onto the reject conveyor 114. However, if the reject gate 49 is in the closed position, this first pair of ejector rollers 113 and 219 drive the carrier sheet across the top surface of the reject gate 49, and the leading edge of the carrier sheet is then seized by a second pair of ejector rollers. The second lower ejector roller 162 is driven and the second upper ejector roll 220 is an idler roller resting thereon. This second pair of ejector rollers then deliver the carrier sheet out onto the delivery conveyor 294 which either conveys the carrier sheet to the delivery mechanism or to the folder, as the case may be. In some cases the length of the carrier sheet or sheets may be less than the distance between the bite of the first pair of ejector rollers 113 and 219 and the bite of the second pair of ejector rollers 162 and 220. To provide for this contingency, both the first upper ejector roller 219 and the second upper ejector roller 220 each consist of a series of thin disc-like rollers, spaced across the width of the machine, with each disc-like roller 219 being mounted on an arm 221 and each disc-like roller 220 being mounted on an arm 222, and each pair of arms 221 and 222 in turn each being pivotally mounted on a cross rod 223, spaced above and in the center of the reject gate 49. There is a groove in the face of each disc making up the rollers 219 and 220, and a rubber O-ring 224 is placed over each pair of discs 219 and 220, and retained in these grooves. The length of the O-ring 224, which is made of rubber, is such that it must be stretched slightly to pass over a pair of the discs 219 and 220. It thus acts to draw the two discs of each pair together, and downwardly, pivoting about the shaft 223. This causes the disc 219 to be held yieldably in contact with the lower driven roll 113, which is continuous across the width of the machine, and the disc 220 to be held yieldably in contact with the lower driven roller 162, which is continuous across the width of the machine. Since both rolls 113 and 162 are driven they thus act to drive the discs 219 and 220, and with them the O-ring 224, and the bottom stretch of the O-ring 224 thus spans the ejector gate 49, so that a carrier sheet which is shorter than the distance between the bite of the first pair of ejector rollers and the second pair of ejector rollers is thus positively driven by the action of two or more O-rings 224, on as many pairs of discs 219 and 220. The reject gate 49 is made up of a series of narrow fingers spaced across the width of the machine, and the pairs of discs 219 and 220, together with an O-ring 224, are each positioned above the space between the fingers that make up the reject gate 49, thus allowing the fingers of the reject gate 49 to raise into the open, or reject, position without interfering with the O-rings 224.

DETAIL OF DETECTION CIRCUITS

FIG. 15 illustrates diagrammatically the circuitry by which each of the sensors 42, 75 and 48 controls the corresponding reject gate. Current energizes the circuit through "black" line 192 and "white" line 193 appropriately connected to an energy source, now shown. One branch of the "black" line 192 leads to a normally closed microswitch 182, the actuating arm

of which is a cam follower roller 181, the width of which spans a pair of split cams 180, which are adjustably mounted on a shaft 179 which makes one complete revolution for each stroke of the associated feeder. The split cams are adjusted so

- 5 that the cam follower roller 181 falls into the dwell of the cams at the time in the cycle when the presence or absence of a carrier sheet or sample is to be detected. During this time the circuit is completed through the microswitch 182 and current may flow therethrough. During the rest of the cycle the cam follower 181 is lifted (as shown in dotted lines) onto the high portion of the split cams 180 and the circuit through the microswitch 182 is broken and no current may flow therethrough.

10 The detector includes a microswitch 184 with a sensor such as 185. There is a manually controlled on/off switch 183 in the circuit so that when detectors are provided for more than one stream the manual switch may be thrown into the on (solid line) position when that particular stream is in fact being used, and into the off (dotted-line) position to deactivate the detector when that stream is not being used. The circuit includes a latching relay 186 with two coils A and B. The reject gate, represented by 189, pivots about the bearings of shaft 190 and is held in the (dotted-line) closed, nonreject, position by 20 spring 188, which acts to hold an arm attached to the pivoted shaft 190 against fixed stop 191. When the solenoid 187 is actuated it overcomes the force of this spring and rocks the pivoted shaft 190 and the reject gate 189 up into the open (solid-line) or reject position.

25 The operation is as follows: Assuming that the manual switch 183 is in the "on" (solid-line) position, at the time when a carrier sheet or sample should be under the detector finger 185 the shaft 179 has rotated to the proper position so that the follower 181 is in the dwell of the cams 180, thereby 30 closing the circuit in the microswitch 182 and allowing current to flow through the manual switch 183 (as shown in solid lines) to the center or common terminal C of the detector microswitch 184. If no carrier sheet or sample is present the detector finger 185 remains down (in the solid-line position) 35 as shown in FIG. 15 and the current flows from the common terminal C through the reed which is shown in the solid-line position and makes contact with the normally closed terminal N.C. on the microswitch which allows the current to flow 40 through coil B of the latching relay 186. This draws the movable member 194 in the switch of the latching relay down toward coil B and into contact with the lower contact 195, where it is latched in this position and remains until coil A is excited. While the movable member 194 in the switch of the 45 latching relay remains in contact with the lower contact 195, current flows through the solenoid 187 and the gate 189 is thereby drawn into the solid-line position as shown in FIG. 15, which is the open or reject position. The dwell on the split cams 180 is set so that microswitch 182 is closed, and current 50 flows therethrough, shortly after a properly fed carrier sheet or sample has reached the point where its presence or absence should be detected by detector finger 185, and the cam follower 181 is lifted again, and the circuit through microswitch 182 is broken, shortly before a properly fed carrier sheet or 55 sample leaves the position where its presence or absence should be detected by detector finger 185.

60

Therefore, continuing the description above, as the conveyor moves, so that the position where the carrier sheet or sample should have been passes beyond the position of detector 185, the cam follower roller 181 is lifted onto the high portion of the cams 180 and current ceases to flow through microswitch 182. This causes current to cease to flow through coil B of the latching relay, but since the movable member 194 of the latching relay switch is latched in position, in contact 185 with the lower contact 195, current continues to flow through the solenoid 187 and the reject gate 189 is held in the open or reject position. When the next carrier sheet or sample should be in position under detector finger 185 the cam follower roller 181 again drops into the dwell of the cams 180 and allows current to flow through microswitch 182. If, once again,

there is no carrier sheet or sample present the detector finger 185 remains in the down (solid-line) position and current once again flows through coil B of the latching relay for as long as the cam follower 181 is in the dwell of the cams 180. However, since the movable member 194 of the latching relay switch is already drawn toward coil B, and is already in contact with the lower contact 195, it simply remains in this position; current continues to flow through solenoid 187 and the fingers of the reject gate 189 remain in (the solid-line) reject position.

If on the next revolution of shaft 179 a carrier sheet or sample is in position under detector finger 185, so that it is raised into the dotted-line position as shown in FIG. 15 at the time when cam follower 181 drops into the dwell of cams 180 and current flows through microswitch 182, then the contact between the common terminal C in microswitch 184 and the normally closed terminal N.C. is broken and contact is made between the common terminal C and the normally open terminal N.O. of microswitch 184 (as shown by the dotted line position therein). Current then does not flow through coil B, but flows instead through coil A and this unlatches the movable member 194 of the switch in the latching relay 186 and draws it up into the dotted-line position, in contact with the upper contact 196, in which position it is latched and remains until coil B is again excited. In this position the contact between the movable member 194 in the switch in the latching relay and the lower contact 195 is broken, and current ceases to flow through the solenoid 187. The spring 188 then draws the gate 189 into the dotted-line position, as seen in FIG. 15, which is the closed or nonreject position, and the spring then holds the reject gate 189 in this dotted-line position, with the arm attached to the pivot shaft 190 against the fixed stop 191. When the shaft 179 turns so that the cam follower roller 181 is lifted onto the high portion of the cams 180, current ceases to flow through microswitch 182 and therefore ceases to flow through coil A. However, the movable member 194 in the switch of the latching relay 186 is latched in the upper position, in contact with the upper contact 196.

On each succeeding revolution of shaft 179, if a carrier sheet or sample is in position under detector finger 185 at the time that the cam follower 181 drops into the dwell of the cams 180, current flows through coil A, but the movable member 194 of the switch in the latching relay 186 is already latched in the dotted-line position, in contact with upper contact 196, so that no current flows through the solenoid 187 and the spring 188 continues to hold the reject gate in the dotted-line or closed position.

On any revolution of shaft 179 on which a carrier sheet or sample is not in position under detector 185 at the time that the cam follower 181 drops into the dwell of the cams 180, coil B is again excited, as previously described, and the movable member 194 of the switch in the latching relay 186 is drawn down into the solid-line position, in contact with the lower contact 195 causing current to again flow through the solenoid 187. This will again cause the reject gate 189 to move into the open or reject position (solid-line), as previously described.

It will thus be seen that the detector senses for the presence or absence of a carrier sheet or sample only at that point in the cycle when a carrier sheet or sample should be in position under the detector and, further, that the presence of a carrier or sample results in the reject gate moving into, or remaining in, the closed or nonreject position, whereas the absence of a carrier or sample causes the reject gate to remain in, or move into, the open or reject position, and, further, the reject gate continues to remain open, in the reject position, without moving, for so long as carrier sheets or samples are not present at the proper times on successive revolutions of shaft 179, and, conversely, the reject gate remains closed, in the nonreject position, continuously, without moving, when carrier sheets or samples are present on successive revolutions of shaft 179, and only moves from one position to the other when there is a change in status with respect to the presence or absence of a carrier sheet or sample on successive revolutions of shaft 179.

Whenever more than a single stream of samples and/or carrier sheets are to be detected for, a product must be present in each stream in order to cause the reject gate 189 to remain in the closed, or nonreject, position (as shown in dotted lines in FIG. 15), and the absence of a product in any one of the streams causes the reject gate 189 to move into the reject or open position (as shown in solid lines in FIG. 15). To accomplish this a detector switch 184 is provided for each stream, located as previously described; a manual on/off switch 183 is provided for each stream; and a latching relay 186 is provided for each stream. In this case the white line 193 is connected in parallel to each of the latching relays at the point marked with an asterisk, 197, the terminals of the lower contacts 198, which lead to the solenoid 187, are connected in parallel at the point marked with an asterisk, 198, and the lines leading from the microswitch 182 to the common terminals of the manual switches 183 are connected in parallel to the common terminal of the manual switch 183 at the point marked with an asterisk, 199. When so connected, the manual switches 183 are placed in the "on" position for all streams which are to be used at a given time, and in the "off" position for any stream or streams not to be used, and when so set, a product must be present, in position to be detected by the detector 185 at the proper time, in each of the streams being used in order to cause the gate 189 to remain in, or move to, the closed or nonreject (dotted-line) position.

In the case of the detector 48, which controls reject gate 49 in FIG. 1, the detector finger, referred to as 185 in FIG. 15, takes on the form previously described for detector 48; but in all other respects the circuitry and operation are as described above.

The control circuits described above and illustrated in FIGS. 1, 2 and 15 take care of the resulting situation if either the carrier feeder 29, or the sample feeder 90 fails to feed in any stream on any stroke of the machine. The corresponding item or items fed by the other feeder or in another stream are then rejected from the machine, without being damaged and without stopping the machine and are delivered into a reject hopper, from which they may be retrieved and again loaded into the proper feeder, depending upon whether they are samples or carrier sheets.

The other way in which either the sample feeder 90 or the carrier sheet feeder 29 can malfunction is by the feeding of "doubles" (i.e., the feeding of more than a single item in any one stream on any stroke of the feeder). If a "double" is fed by the carrier sheet feeder 29, and is allowed to pass through the machine, a sample is affixed only to the top carrier sheet and the sheet or sheets below the top sheet reach the delivery hopper of the machine without a sample affixed thereto. Also, if the carrier sheets are to be folded after a sample is affixed, "double" carrier sheets may jam in the folder and interrupt the operation of the machine.

If a "double" is fed by the sample feeder 90, and is allowed to pass out onto the sample conveyor 40, only the bottom one of the two or more samples which have been fed together will be picked up by a suction head 38, and the other sample or samples will fall freely after they leave the end of the sample conveyor 40, and may fall into the path of or onto one of the carrier sheets in such a way as to cause a jam-up in the machine; or, worse yet, may fall through the light beam directed by the light 107 on the photocell 108, thereby causing the glue gun 109 to fire at a time when the glue will not be intercepted by a sample carried by a suction head 38, with the result that glue will be fired onto other working parts of the mechanism or onto the surface of a passing carrier sheet, and in either case this can cause the machine to jam up and require extensive cleaning to get it back into normal operation. It has, therefore, been found important, in order to maintain the continued uninterrupted operation of the machine, to insert a "doubles" detector and eliminating device, similar to that illustrated diagrammatically in FIG. 16, between the pullout rollers 70 of the sample feeder 90 and the initial lower tape roller 150 of the sample conveyor 40, and to insert a similar "doubles" detector and eliminator device between the pullout

rolls 57 of the carrier feeder 29 and the initial tape roller 60 of the carrier conveyor 30.

The operation of the "doubles" detector and eliminator device illustrated in FIG. 16 is as follows. The pullout rollers of the feeder involved deliver the sample or carrier sheet, as the case may be, onto a series of driven conveyor rollers 206. There is one or more idler rollers (not shown in FIG. 16) directly above each of the driven rollers 206 to hold the sheets in contact with the driven rollers 206, and thereby cause the sheets to be positively driven and conveyed by these conveyor rollers 206. Also mounted above the first of these driven conveyor rollers 206 and at approximately the center of the sheet (from side to side) is a free-turning detector roller 203 supported on a pivoted arm, which pivots about a shaft 204, and has a longer right angle extension 205 which multiplies any lifting action against roller 203, and which bears against the detector of a microswitch 202. The microswitch 202 and the pivot shaft 204 are mounted together on a plate, which in turn is vertically adjustable, in micrometer increments, so that the distance between the free-turning roller 203 and the driven conveyor roller 206 below it can be varied by increments of 0.001 inch or less. This adjustment is normally set to allow the passage of a single sheet between the free-turning detector roller 203 and the driven conveyor roller 206 below it, without lifting the roller 203 about the pivot point 204. If more than a single sheet then passes under the detector roller 203, it is lifted about the pivot point 204, causing the upwardly projecting arm 205 to depress the detector button on the microswitch 202.

There is a deflector gate 207 located in the path of the sheets beyond the last of the driven conveyor rollers 206, and over which single sheets normally pass onto the associated conveyor beyond. The distance between the detector roller 203 and the deflector gate 207 is sufficient to allow the deflector gate 207 to react to a single sheet initiated by the detector roller 203, and to be positioned either in the closed position (full-line position) to cause the sheets to pass thereover, or in the open position (dotted-line position) to deflect the sheets into a reject hopper (not shown), below and beyond the deflector gate 207.

The operation is as follows. Current energizes the circuit through a "black" lead 200 and a "white" lead 201 which are appropriately connected to an energy source, not shown. Current from the black lead 200 flows to the common terminal of the microswitch 202. A line leads from the normally open terminal of the microswitch to one side of the coil of solenoid 211, and the other side of the coil of the solenoid 211 leads to the "white" line 201. As long as only single sheets (or no sheets) pass beneath detector roller 203, microswitch 202 remains in the normally open condition, as shown by the full-line position of the movable leaf in microswitch 202 in FIG. 16, and therefore no current flows through the coil of solenoid 211 and spring 210 acts on an arm, extending from the pivot shaft 208 of the deflector gate 207, to hold the arm up in contact with fixed stop 209, so that deflector gate 207 remains in the full-line, or closed, position as seen in FIG. 16. Single sheets therefore pass over the deflector gate 207 and onto the conveyor which follows. Whenever more than a single sheet passes under detector roller 203 the roller is lifted, and pivots about the center of shaft 204, causing the arm 205 to depress the detector button on microswitch 202, thereby causing the movable leaf therein to move into the dotted-line position as seen in FIG. 16, so that current flows through the microswitch and thence through the coil of solenoid 211, which actuates the solenoid and causes it to pull the arm of the deflector gate 207 down, against the action of spring 210, so that deflector gate 207 is moved up about pivot 208 into the dotted-line position, and the arm projecting outwards from the pivot shaft 208 similarly moves down into the dotted-line position, as seen in FIG. 16. When the leading edges of the double or multiple sheets reach the deflector gate 207 they are deflected downward thereby, into a reject hopper (not shown in FIG. 16) below and beyond deflector gate 207. When the solenoid

211 acts to draw the deflector gate 207 into the open or reject position (the dotted-line position), the end, 212, of the arm projecting from pivot shaft 208 is drawn down, and in turn spring 218 causes the angular latching arm 213 to pivot about shaft 215 until the cutout portion 214 of the latching arm 213 moves into position over the end, 212, of the arm projecting from the pivot shaft 208. This latches the deflector gate 207 in the open (dotted-line) position and holds it there, even after the trailing edge of the multiple sheets have passed beyond the detector roller 203. When the trailing edge of the multiple sheets passes out from under detector roller 203 the microswitch 202 returns to the normally open position and current ceases to flow through solenoid 211, so that spring 210 would then return the deflector gate to the closed (full-line) position but for the latching action of the cutout portion 214 in the pivoted right-angle latching arm, 213 which continues to hold the deflector gate 207 in the open (dotted-line) position. Shaft 217 makes one complete revolution for each feeding stroke of the feeder and carries a cam 216, located below the horizontal arm of the right-angle latching arm 213. The hump on this cam 216 acts to lift the horizontal arm of the right-angle latching arm 213, and pivot it around the pivot point 215, after the trailing edge of the longest sheet that may be handled by the feeder has had time to pass beyond the last of the driven conveyor rollers 206, and at this point the lifting action of the cam 216 acts to unlatch the end, 212, of the arm projecting from the pivot shaft 208 of the deflector gate 207, so that the deflector plate 207 may then return to the closed (full-line) position, under the action of the spring 210 which pulls the projecting arm into contact with the fixed stop 209.

When more than a single stream is to be fed from either feeder a separate detector roller 203, together with associated mechanism, and a separate microswitch 202 is provided for each stream, and the microswitches are wired in parallel across the terminals marked with asterisks 228. When so wired, if a double is fed in any one of the streams solenoid 211 is actuated and the gate 207 is moved into the open (dotted-line) position as seen in FIG. 16, and the sheets fed in all streams on that stroke of the feeder are then deflected by the deflector plate 207 into the reject tray (not shown). If such detectors are provided for more than a single stream, but less than the total number of streams are in use at any given time, no provision is required to deactivate the detectors in the unused stream or streams since no sheets will be passing under the detector roller 203 in such streams, and only the presence of more than a single sheet in one of the streams being used will cause the solenoid 211 to be activated.

It should be noted that with the use of the two types of control mechanisms described, in connection with FIGS. 15 and 16, provision is made for handling any malfunction of either feeder, whether a misfeed or the feeding of a "double," in any stream, without stopping the machine and with the rejected carrier sheets or samples being removed from the machine undamaged and ready for reuse.

In connection with the mechanism of FIG. 16, provisions for carrying short sheets across the deflector gate 207 may be made similar to those described in connection with the deflector gate 49 at the delivery end of the machine in FIG. 1.

MACHINE DRIVE

FIG. 17 is a plan view illustrating diagrammatically the drive for the machine. As has previously been pointed out, it is possible to operate the machine in what is referred to as the "single lugged" mode of operation or in what is referred to as the "double lugged" mode of operation.

When running "single lugged" the lugs 33, carried by the carrier sheet conveyor timing chains 32, are spaced apart by a distance exactly equal to one-half the circumference 151 of the sample transfer wheel 35. When running "single lugged" carrier sheets of any length up to approximately 1 inch shorter than one-half the circumference 151 of transfer wheel 35 may be handled. In this case the carrier sheet feeder 29 is timed to

feed two sheets for each complete revolution of the sample transfer wheel 35, and normally the sample feeder 90 is also timed to feed one sample for each carrier sheet. In other words, when running "single lugged" the sample feeder 90 also feeds two samples for each complete revolution of the sample transfer 35, with the samples being picked off the sample conveyor 40 and transferred to the affixing point 154 by suction heads 38a and 38c, with suction heads 38b and 38d being unused in this case.

However, when running "single lugged," if the carrier sheets are somewhat longer than one-quarter of the circumference 151 of sample transfer wheel 35, it is possible to time the sample feeder to feed four samples for each complete revolution of sample transfer wheel 35, or in other words two samples for each carrier sheet in each stream. In this case the two samples placed on each carrier sheet would be directly in line, one behind the other, and would be spaced apart from each other by exactly one-quarter of the circumference 151 of sample transfer wheel 35.

It is, of course, also possible to place two samples side by side on a single carrier sheet by handling two streams of samples for each stream of carrier sheets, and in this instance the side by side spacing between the samples can be varied as desired. A sample may be positioned at any point across the width of the carrier sheet by sliding the sample transfer wheel 35 from side to side along its mounting shaft 13 to any desired point. The stationary member 92, of the sample transfer wheel mechanism, moves with the rotating disc member 35. The pull-out rolls, shuttle blade and magazines of the sample feeder 90 may be similarly aligned from side to side to correspond with the selected position of a sample transfer wheel 35. It is also possible to adjust the position of the sample to any position on the carrier sheet with respect to the leading edge of the carrier sheet by moving the sample to or from the leading edge of the carrier sheet in a manner that will be described in connection with the more detailed description of the drive mechanism which is to follow.

When the length of the carrier sheets being handled is no more than approximately 1 inch shorter than one-fourth of the circumference 151 of the sample transfer wheel 35, it is then possible to feed four carrier sheets and four samples for each complete revolution of the sample transfer wheel 35 without increasing the surface speed of the carrier sheet conveyor 30 or of the sample conveyor 40, and without increasing the circumferential speed, at circumference 151, of sample transfer wheel 35. This is accomplished by spacing the lugs 33 on lug carrying chain 32 at a distance from each other equal to exactly one-quarter the circumference 151 of sample transfer wheel 35, and timing both the carrier feeder 29 and sample feeder 90 to each feed four sheets for each complete revolution of the sample transfer wheel 35. In this case, of course, all four of the suction heads 38, on the sample transfer wheel 35, are used. This mode of operation is referred to as "double lugged" operation.

Referring now to FIG. 17: the various major driving and driven shafts are shown diagrammatically in plan view, spanning the main frames 28, the frames of the carrier sheet feeder 29 or the frames 119 of the sample feeder 90, and journaled therein. The drive for the various components of the machine emanates from output shaft 18 of speed reducer 52, the input shaft of which is driven by pulleys and a belt 230 from the drive motor 51.

Driven sprocket 232 on shaft 16 is driven by means of chain 233 from drive sprocket 231 on shaft 18. Shaft 16 makes two revolutions for each revolution of shaft 18. At one end of shaft 16 a sprocket 234 drives a chain 236 which in turn drives sprocket 235 affixed to shaft 17. The lower pullout rolls 57 of the carrier sheet feeder 29 are mounted on shaft 17. Also mounted on shaft 17 is a sprocket 237 which drives chain 239 which in turn drives sprocket 238, which is mounted on the shaft of the conveyor tape roller 60, which in turn drives the conveyor tapes 31 of the carrier sheet conveyor 30. The conveyor tapes 31 extend between the driving conveyor tape

roller 60, at the carrier sheet feeder end of the machine, and conveyor tape roller 62 near the delivery end of the machine. Conveyor tape roller 62 is an idler roller driven by the conveyor tapes 31. Conveyor tape roller 60 is driven at a speed which causes the conveyor tapes 31 to move somewhat faster than the lug-carrying chain 32, as previously described.

Also mounted on shaft 16 is a sprocket 240 which drives a chain 242 which in turn drives a sprocket 241 mounted on shaft 25, which carries the second lower ejector roller 162. At 10 the other end of shaft 25 a sprocket 243 drives a chain 245 which in turn drives sprocket 244, which is mounted on shaft 24 which carries the first lower ejector roller 113. Shafts 24 and 25, and with them ejector rollers 113 and 162, are both driven at the same speed, and at a speed considerably faster than the speed of the adjacent conveyor tape roller 62.

Also mounted on shaft 16 are the sprockets 63 for the lugged chains 32. The lugged chains 32 also pass over sprockets 100, which are mounted on idler shaft 21 near the carrier sheet feeder end of the machine. Shaft 21 is an idler shaft driven by the chains 32.

The speed of shaft 16 and the size of the sprockets 63 are such as to cause the lug carrying chains 32, and the lugs 33 mounted thereon, to travel at a surface speed exactly equal to 20 the circumferential surface speed of the sample transfer wheel 35, at circumference 151.

At the other end of shaft 16 there is a sprocket 246 which drives chain 248, and, through it, sprocket 247 mounted at one end of shaft 14. Sprocket 246 has a large hub, and is 30 secured to shaft 16 by means of two large set screws 249, at right angles to each other, through this hub; and by means of which sprocket 246 may be angularly adjusted around shaft 16 for a purpose that will be more fully explained hereafter. Shaft 14 is driven at a speed that causes it to make one revolution 35 for each revolution of shaft 18. Between the side frames 28, in which it is journaled, shaft 14 is surrounded by a stationary tube 94 journaled on the shaft. The upper and lower arms of the stationary member 92, of the product transfer wheel mechanism, project above and below this stationary tube 94, thereby holding member 92 stationary, and preventing it from turning about the hub of rotating transfer wheel 35 on which it is journaled.

Another sprocket 250, mounted on shaft 14, drives chain 252 and through it drives sprocket 251, mounted on cam shaft 45 15. Cam shaft 15 carries the split cams 105 which control the valves for the suction manifold, as seen and described in FIGS. 4 and 5. Shaft 15 is driven at a speed which causes it to make one complete revolution for each two revolutions of shaft 18.

Also mounted on shaft 14 is a gear 253, which meshes with 50 another gear 254 which is mounted on the sample transfer wheel shaft 13. The sample transfer wheels 35 are mounted on shaft 13, and shaft 13 is driven at a speed which causes it to make one complete revolution for each two revolutions of shaft 18. Mounted at the other end of shaft 13 is a sprocket 55 255 which drives chain 257 and through it sprocket 256 mounted on the end of shaft 20. Shaft 20 carries the driven lower conveyor tape roll 150 of the sample conveyor 40; and the lower conveyor tapes 45 of the sample conveyor 40 pass over 60 and are driven by roller 150. There is also a sprocket 258 on shaft 20 which drives chain 115, and through it drives sprocket 259 on shaft 101, on which the lower pullout rolls 70 of the sample feeder 90 are mounted. Chain 115 also drives the upper pullup roller shaft and the shaft 82 for the upper 65 sample conveyor tape roller 83 as seen in FIG. 2, but not shown in FIG. 17.

At one end of shaft 14 there is a gear 260 which meshes with an intermediate gear 122 which in turn drives gear 261 mounted on shaft 12. Gear 261 is a change gear and two interchangeable gears are provided, one of which causes shaft 12 to rotate at a speed such that it makes one complete revolution for each complete revolution of shaft 18 and the other of which causes shaft 12 to rotate at a speed such that it makes two complete revolutions for each revolution of shaft 18. The first of these gears is used when the machine is running in the

"single lagged" mode, and one sample is being affixed to each carrier sheet, and the second gear is used when the machine is being run in the "double lagged" mode, or when two samples are being affixed to each carrier sheet, in each stream of samples. As seen in FIG. 1 as well as in FIG. 17, intermediate gear 122 is journaled on a stud 191 mounted on a pivoting mounting plate 262. Mounting plate 262 is journaled on shaft 14 and may be adjustably rotated about the center of shaft 14. Mounting stud 291 is so located that intermediate gear 122 remains in mesh with gear 260 at all times, as mounting plate 262 rotates about shaft 14. Mounting plate 262 is rotated to also bring intermediate gear 122 into mesh with whichever one of the two change gears, 261, are mounted on shaft 12, and mounting plate 262 is then locked into position with nut 292. Also mounted on shaft 12 is a sprocket 263 which drives a chain 265, which in turn drives sprocket 264 on shaft 19. Sprockets 263 and 264 are of the same size, so the shaft 19 is driven at the same speed as shaft 12. Split cams 74 are mounted at one end of shaft 19 and these are the cams which activate the linkage 145 which controls the action of the stop fingers 39 at the end of the sample conveyor 40, as seen in FIG. 2.

Also on shaft 12 is sprocket 266 which drives chain 263, which in turn drives sprocket 267 on shaft 23. Sprockets 266 and 267 are of the same size, so that shaft 23 is driven at the same speed as shaft 12. Shaft 23 carries the split cams 78 for the lifter mechanism illustrated in FIGS. 6 and 7, of the sample feeder 90 and cam 141 of the mechanism illustrated in FIG. 11. Also mounted on shaft 12 is a timing belt sprocket 269 which drives a timing belt 271, and through it another timing belt sprocket 270 on the input shaft of a right-angle gear box 272, the output shaft of which is shaft 179a, corresponding to shaft 179 of FIG. 15, on which are mounted split cams 180a (all within the cam housing 273 which also mounts the microswitch 182a corresponding to microswitch 182 of FIG. 15). The cams and microswitches in control box 273 are tied in with detectors 42 and 75 of FIG. 2. Shaft 179a rotates at the same speed as shaft 12.

At the end of shaft 12 opposite from gear 261 is mounted a driving disc 274, in which a crank pin 275 is mounted at a distance from the center of shaft 12, so that crank pin 275 imparts a reciprocating motion to the linkage 73 which drives the shuttle slide rod 72 of the sample feeder 90, as seen in FIGS. 1 and 2.

There is a sprocket 276 on shaft 18 which drives chain 278, which in turn drives a sprocket 277 on shaft 11. Sprockets 276 and 277 are of the same size, so that when chain 278 is used to drive sprocket 277 from sprocket 276, shaft 11 makes one complete revolution for each revolution of shaft 18. This is the way in which shaft 11 is driven when the machine is being operated in the "single lagged" mode. Alongside sprocket 276 on shaft 18 is another sprocket 279 of the same size. In line with sprocket 279 and affixed to shaft 11 is another sprocket 280, one-half the size of sprocket 279. When the machine is to be operated in the "double lagged" mode, the chain 278 is removed from the sprockets 276 and 277 and another chain, of the proper length, connects sprockets 279 and 280, so that shaft 11 then makes two revolutions for each revolution of shaft 18. At one end of shaft 11 is a timing belt sprocket 284 which drives a timing belt 286, which in turn drives another timing belt sprocket 285 on a shaft 179b of control box 293 which contains split cams 180b and microswitches 182b, corresponding to 179, 180 and 182 respectively in FIG. 15, with the cams and microswitches in control box 293 being associated with detector 48 of FIG. 1. Affixed to the other end of shaft 11 is a driving disc 281 which carries a crank pin 282, mounted at a distance from the center of shaft 11, and which imparts the reciprocating motion to the linkage 283 which operates the shuttle, or other timed mechanism, of the carrier sheet feeder 29.

Also on shaft 18 is a sprocket 287 which drives chain 54 which in turn drives sprocket 288 affixed to shaft 22. Sprockets 287 and 288 are of the same size and, therefore,

when connected with chain 54, shaft 22 is driven at the same speed as shaft 18. This is the driving arrangement for shaft 22 which is used when the machine is being operated in the "single lagged" mode. There is another sprocket 289, mounted on the same hub with sprocket 288. Sprocket 289 is one-half the size of sprockets 287 and 288. When the machine is to be operated in the "double lagged" mode, set screw 290, which holds the hub of sprockets 288 and 289 to shaft 22, is loosened and sprockets 288 and 289 are moved inwardly along shaft 22 until sprocket 289 is in line with sprocket 287 on shaft 18. Chain 54 is then used to connect sprockets 287 and 289, and a third, chain tightener, sprocket (not shown) is used to take up the slack in chain 54. Shaft 22 is then driven at a speed which causes it to make two complete revolutions for each revolution of shaft 18. This is the method used for driving shaft 22 when the machine is being operated in the "double lagged" mode. Split cams 93 which operate the lifter mechanism (illustrated in FIGS. 6 and 7) for the carrier sheet feeder 29 are mounted on shaft 22.

It will thus be seen that the lug-carrying conveyor chains 32, the conveyor tapes 31, the pullout rollers 57 for the carrier sheet feeder 29, the ejector rollers 113 and 162, the cam shaft 15, the sample conveyor tapes 45, the pullout rollers 70 for the sample feeder 90 and the sample transfer wheel 35 all operate at the same fixed speed relationship to drive shaft 18 irrespective of whether the machine is being operated in the "single lagged" mode or in the "double lagged" mode.

Two chain drives, 278 and 54, must be changed as described to change the carrier sheet feeder 29 and associated mechanisms from "single lagged" to "double lagged" operation, or vice versa. The change gear 261 must be changed to change the sample feeder and associated mechanisms from "single lagged" to "double lagged" operation, or vice versa.

In order to adjust the position of the sample on the carrier sheet toward or away from the leading edge of the carrier sheet, set screws 249 in the hub of sprocket 246 are loosened, to disengage sprocket 246 from shaft 16. Then, while shaft 18 is held stationary, shaft 13 is rotated, either clockwise or counterclockwise as seen from the right side of FIG. 17, depending on whether the position of the sample is to be moved away from the leading edge of the carrier sheet or toward the leading edge of the carrier sheet. When the desired position has been reached, set screws 249 in the hub of sprocket 246 are again tightened to firmly engage sprocket 246 to shaft 16 again, in the new position. When this single adjustment is made, all elements of the timing of the sample feeder 90 and the sample conveyor 40, and associated controls, are automatically adjusted along with the relative position of the suction heads 38, on the sample transfer wheel 35, and the machine will then operate, without further adjustment, to place the sample in the newly selected position with respect to the leading edge of the carrier sheet, while all of the relationships between the carrier sheet feeder 29 and the carrier conveyor 30, and associated controls, have been left undisturbed.

The embodiments of this invention in which an exclusive property or privilege is claimed are defined as follows:

1. Apparatus for applying and affixing an article to a carrier sheet as a continuous operation which comprises: means for feeding carrier sheets at a given rate in timed and registered, spaced relationship along a conveyor surface; a magazine adapted to contain a plurality of the articles which are to be applied to the carrier sheet; an article applying and affixing device positioned between said magazine and said conveyor surface; means for extracting individual articles from said magazine and delivering them to said device; means associated with said article applying and affixing device for registering each article on the device with respect to the position of a carrier sheet that is moving along said conveyor surface; means for applying an adhesive to each article as it is on said device or to the carrier sheet that is to receive said article; means including said article applying and affixing device for moving each article into engagement with a carrier sheet, and

means for conveying the combined carrier sheet and article to a delivery point, the means for extracting articles from the magazine and for delivering them to said article applying and affixing device comprising shuttle feeder means including a reciprocable shuttle having an article-engaging surface characterized by a high coefficient of friction, and means for retaining an article to be fed on said friction surface when the shuttle is moved in article-feeding direction, and means for physically separating said friction surface from the next article to be fed when the shuttle is making its return stroke.

2. The apparatus in accordance with claim 1 wherein said article extractor means comprises a reciprocating shuttle to extract individual articles from said holding means, said shuttle being connected to a periodically actuated vacuum source and said holding means being an open-sided magazine which may be filled with articles while the apparatus is in continuous operation and having a forward member, a portion of which forms an adjustable gate to thereby allow the feeding of only a single article therefrom.

3. The apparatus in accordance with claim 1 wherein said article extractor means comprises a shuttle-type feeder having a reciprocating shuttle blade having a high coefficient of friction material on the surface of said shuttle blade to come in contact with the exposed undersurface of said article to thereby effectively feed individual articles and additionally including periodically actuated means to impart lifting movement to the stack of articles contained in the magazine on said article-holding means during the backward stroke of said shuttle blade.

4. The apparatus in accordance with claim 1 wherein said means for separating and feeding said carrier sheets is adjustable with respect to the axis of said apparatus in order to provide for different length, width and thickness of said carrier sheets and said hopper is adapted to be continually loaded while said apparatus is in operation and additionally includes means for detecting when more than a single carrier sheet has been fed onto said conveyor surface and for deflecting an unwanted multiple sheet from the path followed by a single wanted sheet without stopping or interrupting the operation of said apparatus.

5. The apparatus in accordance with claim 1 wherein said conveyor surface includes means adapted to carry sheets through said apparatus in timed relationship to other elements thereof and being further adapted to carry one or a plurality of belts or chains having a number of uniformly spaced lugs projecting outwardly therefrom and which length is an exact multiple of the spacing between said lugs.

6. The apparatus in accordance with claim 5 wherein the spacing of said lugs is selective and they may be a unit distance apart or one-half said unit depending upon the length of said carrier sheets and additionally including means for driving said lug-carrying belts or chains at a uniform surface speed.

7. The apparatus in accordance with claim 6 which additionally includes nonlugged conveyor tapes to aid in supporting and conveying carrier sheets and being adapted for parallel travel to said lugged belts or chains and feeder adjustment means to adjust the timing of the carrier feeder to cause it to feed individual carrier sheets onto said conveying surface between a lug or lugs ahead and a lug or lugs behind and in a selected spaced relationship to either lugs ahead or behind.

8. The apparatus in accordance with claim 7 including conveyor control means for causing said carrier sheet fed onto said conveyor surface to travel at a speed faster than said lugs until its leading edge contacts the lugs ahead and to thereafter move along the said conveyor surface at the same speed as said lugs and with its leading edge continually in contact with said lugs ahead.

9. The apparatus in accordance with claim 8 wherein said means for supporting said nonlugged conveyor tapes are adapted to position said tapes above the upper surface of said lugged carrying belts or chains and said nonlugged conveyor tapes or chains are driven at a surface speed greater than the surface speed of lugged carrying belts or chains.

10. The apparatus in accordance with claim 9 which additionally includes means to urge the carrier sheets into frictional contact with the top surface of said nonlugged conveyor tapes and one or more downwardly projecting stationary fingers are mounted above the main conveyor surface with their lower ends just above the path followed by the top surface of a properly fed carrier sheet to position said carrier sheet between spaced pairs of lugs on said lugged carrying chains or belts whereby a carrier sheet fed and improperly positioned on top of a lug or lugs will contact the finger or fingers and be held back to thereby cause said carrier sheet to fall onto said conveyor surface between spaced pairs of lugs.

11. The apparatus in accordance with claim 9 including means for causing a carrier sheet fed onto said conveyor surface to pause or travel at a speed slower than said lug or lugs until its trailing edge is contacted by the lug or lugs behind and thereafter move along the main conveyor surface at the same speed as said lugs and with its trailing edge continually in contact with said lug or lugs behind.

12. The apparatus in accordance with claim 11 including means for driving said lugcarrying belts or chains and said nonlugged conveyor tapes at the same surface speed and yielding means to hold back a carrier sheet fed onto the main conveyor surface between a lug or lugs ahead and a lug or lugs behind until the trailing edge of said carrier sheet is contacted by the lug or lugs behind thereby pushing the sheet to free it from the yielding hold back means; thereafter carrying the sheet throughout the length of the main conveyor surface at the same surface speed as the nonlugged conveyor tapes and the lugged carrying belts or chains and with its trailing edge continually in contact with the lug or lugs behind.

13. The apparatus in accordance with claim 12 which includes means to urge one side edge of the carrier sheets into contact with an adjacent side guide member positioned along one side of their path of travel adjacent said main conveyor surface and to thereafter yieldably hold this side edge in contact with said adjacent side guide throughout their passage along said conveyor surface.

14. The apparatus in accordance with claim 1 which includes article-feeding means mounted at a level higher than the surface of said conveyor surface for separating and feeding single articles from said hopper containing a supply of said articles in timed relationship to other elements of said apparatus.

15. The apparatus in accordance with claim 14 wherein said article-feeding means is adjustable to accommodate articles of different length, width and thickness and is adapted so that articles may be loaded into said hopper while said apparatus continues to run and includes detecting means for detecting when more than a single article has been fed and for deflecting such multiple articles from said path followed by single articles without stopping or interrupting the operation of said apparatus.

16. The apparatus in accordance with claim 15 including register means for positioning single articles into register to a selected position on a single carrier sheet and for pressing them into contact with said carrier sheets at this position as both the articles and carrier sheets move past a common affixing point on said conveyor surface at the same surface speed.

17. The apparatus in accordance with claim 16 wherein said means for bringing said article into register with said selected position comprises a timing belt or chain mounted to run at the same surface speed as said lugged carrying belts or chains of said main conveyor surface supported by spaced sprockets from the path on which said articles are conveyed and with outwardly projecting lugs uniformly spaced apart by the same distance as the distance between the lugs on the lug-carrying belts or chains of said main conveyor surface with the greater number of lugs and including means whereby the trailing edge of each article is contacted by one of these lugs and driven by it into said registered position and at the same surface speed as the preselected position on said carrier sheet to which it is to be affixed.

18. The apparatus in accordance with claim 16 wherein said article conveyor means for receiving individual articles in timed relationship from said article feeder conveys said articles to a predetermined position in timed and registered relationship to the selected position on the carrier sheets at which they are to be affixed, said article-conveying means including means to register and position said articles from side to side and from front to back register including stop finger means which pivot into the path of these articles and by which the leading edge thereof is stopped and registered at said predetermined position after which said article is picked up and moved ahead in registered position by said article applying and affixing device and said stop finger means simultaneously pivot out of the path to be followed by said article.

19. The apparatus in accordance with claim 18 wherein said means to position and register said article is independently adjustable in relation to said article transfer wheel and said article feeder is independently adjustable with respect to the timing thereof with regard to the timing of said article positioning and registering means of said article conveyor.

20. The apparatus in accordance with claim 19 including means for independently adjusting the timing of said carrier sheet feeder in relation to the said sheet positioning and registering means of said main conveyor surface including means for adjusting the position at which said article transfer wheel applies an article to a carrier sheet in relation to the leading edge of a carrier sheet whereby the independent adjustability does not disturb the adjustment of said article positioning and registering means of said article conveyor with respect to said transfer wheel or the adjustment of the timing of said article feeder to said article positioning and registering means of said article conveyor or the adjustment of the timing of said carrier sheet feeder to said sheet positioning and registering means of said main conveyor surface or position at which the adhesive is supplied in relation to the final positions of the article and carrier sheet to each other after the article has been affixed to the carrier sheet and which additionally includes means to independently adjust the side-to-side positioning of the articles on said carrier sheet.

21. The apparatus in accordance with claim 1 wherein said article applying and affixing device includes an article transfer wheel mounted between said article conveyor and said main conveyor surface and positioned to be tangent to the plane of the upper article supports of said article conveyor at a predetermined point and to the plane of the top surface of a carrier sheet carried on said main conveyor surface at said affixing point.

22. The apparatus in accordance with claim 21 wherein the effective circumference of said article transfer wheel is an even multiple of the distance between said lugs on said lug-carrying belts or chains on said main conveyor surface and an even number of spaced suction heads are carried by said wheel about the periphery thereof such that the distance between any two suction heads measured around the effective circumference of said wheel is equal to the distance between the lug or lug-carrying belts or chains of said main conveyor surface, each of said heads being radially adjustable toward and away from the center of said article wheel so that the outer surface of an article carried by one of said suction heads will lie at the effective circumference of the article transfer wheel whereby by the adjustment of said suction heads adjustment for a wide range of article thicknesses is achieved.

23. The apparatus in accordance with claim 21 wherein when an article reaches said predetermined point on said article conveyor, it is held between upper and lower support members and said upper support member or members lies in a plane tangent to the effective circumference of said article transfer wheel and said lower support member or members are adjustable toward and away from the center of said article transfer wheel so that they may be set at a distance from the upper support members equal to the thickness of said article whereby said suction head of said article transfer wheel will just contact the bottom surface of a article at said predetermined point.

24. The apparatus in accordance with claim 23 wherein each of said suction heads are connected to an individual vacuum source and the suction is controlled by valves and cams such that vacuum is created and independently drawn in each of said suction heads as it reaches said predetermined point where the upper supports of said article conveyor are tangent to the effective circumference of said article transfer wheel and said vacuum is independently discontinued or broken when said suction head reaches said affixing point and said carrier sheet at said point is supported from below in at least the area to which the article is to be affixed to said carrier sheet, said support comprising a platen belt or roller member which is driven at the same surface speed as said carrier sheet and which member is adjustable toward and away from the center of said article transfer wheel whereby the top surface of carrier sheets of different thicknesses may be maintained in a plane tangent to the effective circumference of said article transfer wheel.

25. The apparatus in accordance with claim 1 including means for causing the combined carrier sheets and affixed articles to pass between upper and lower squeeze means immediately after passing said affixing point and to continue to be held together by said squeeze means as they are conveyed to the end of said main conveyor surface to thereby hold said article and carrier sheet firmly in contact with each other without disturbing their relative positions while said adhesive takes an initial set.

26. The apparatus in accordance with claim 1 which includes detector means for sensing for the presence or absence of a carrier sheet on the main conveyor surface prior to the carrier sheet reaching the affixing point and means for deflecting articles from the normal path followed by articles and into a reject hopper whenever it is detected that the carrier sheet to which the article would be affixed is not present, said deflector being spaced back from the affixing point along the path followed by articles by a distance greater than the distance from the point at which adhesive is applied to either the article or carrier sheet to said affixing point.

27. The apparatus in accordance with claim 1 which additionally includes detector means for sensing for the presence or absence of a carrier sheet in the main conveyor surface prior to the carrier sheet reaching the affixing point and means for deflecting articles from the normal path followed by articles into a reject hopper whenever it is detected that the carrier sheet to which the article would be affixed is not present, said deflector means being spaced back of said affixing point along said main conveyor surface by a distance greater than the distance from the affixing point to the deflector means measured along the path followed by said articles.

28. The apparatus in accordance with claim 27 wherein the control of said deflector means by said detector is such that when the machine runs with no carrier sheets being fed, the deflector means remains in the reject position and when the machine runs, with a continuous uninterrupted flow of carrier sheets being fed onto the main conveyor surface, the deflector remains out of the path followed by the article and moves into the reject position only when a carrier sheet is detected to be absent, then returns to the nonreject position only when a carrier sheet is next detected to be present.

29. The apparatus in accordance with claim 1 including means to control said means for applying an adhesive so that adhesive is only applied whenever both article and carrier are both present.

30. The apparatus in accordance with claim 1 including means to cause a carrier sheet to which no article has been affixed to be deflected into a reject hopper instead of following the path followed by carrier sheets to which articles have been affixed out onto the delivery conveyor, said means including a deflector gate and including means to carry carrier sheets which are shorter than said deflector gate on over said gate and out onto said delivery conveyor when said gate remains closed.

31. The apparatus in accordance with claim 1 including means to feed more than a single stream of articles in side-by-

side relationship and to affix multiple articles to a single carrier sheet.

32. The apparatus in accordance with claim 1 including means to feed more than a single stream of articles in side-by-side relationship and more than a single stream of carrier sheets in side-by-side relationship whereby one or more articles are affixed to each carrier sheet.

33. The apparatus in accordance with claim 32 wherein detector means are placed along the path followed by articles to detect the presence or absence of an article and is spaced back from an affixing point of said carrier sheet and said article along the path followed by articles by a distance equal to the distance back from the affixing point along the main conveyor surface to the detector.

34. The apparatus in accordance with claim 33 which includes coating detector means to detect for the presence or absence of a carrier sheet in said stream and to cause the deflector for articles to move into the reject position whenever any sample in any stream of articles and/or carrier sheet is absent.

35. The apparatus in accordance with claim 34 including control means whereby carrier sheets without articles affixed thereto are deflected into a reject hopper and adhesive is applied only when both article and carrier sheet are detected to be present and whereby only carrier sheets with properly affixed articles thereto are delivered onto the delivery conveyor and all such other carrier sheets or articles are otherwise deflected and/or rejected from the normal stream.

36. The apparatus in accordance with claim 1 including means whereby said carrier sheets with articles affixed thereto are delivered into the bite of a folding machine as they leave said main conveyor surface.

37. The apparatus in accordance with claim 1 wherein said means for extracting individual articles from said magazine includes a suction shuttle member for separating and feeding single objects comprising a suction shuttle blade narrower than the width of the object's suction openings in the top face of said blade, a hopper to hold a supply of such objects above said blade with the bottom object in the hopper resting on the top surface of said blade, means to reciprocate the blade, means to cause suction to be drawn at the openings in said top surface of said blade when it reaches the back of its stroke thereby causing said bottom object in said hopper to be drawn down intimate contact with the top surface of said blade, gate means adjustably spaced from said blade at the front of said hopper, said gate means including a downwardly projecting member adjustable spaced from the top surface of said blade by a distance just sufficient to allow the passage of a single object therethrough, upper and lower pullout rollers beyond said gate on either side of said blade between which said blade passes on its forward stroke so that the leading edge of said object is seized by the bite of said pullout rollers and means to cause the vacuum to be broken in said suction shuttle blade to release the object from said blade just as its leading edge is seized by said pullout rollers so that said pullout rollers carry the object out onto a conveyor as said blade begins its backward stroke.

38. The apparatus in accordance with claim 37 which includes lifter fingers spaced on either side of said blade under the objects in said hopper, the tops of said fingers being normally below the level of the top of said blade and means to lift said fingers and thereby the objects in the hopper as said blade begins its backward stroke and the trailing edge of said object just withdrawn passes the position of said gate such that the lower surface of said bottom object in said hopper is held out of contact with the surface of said blade during the backward stroke of said blade and including means for lowering said fingers to drop the objects onto said blade at the point where said blade reaches the back of said stroke and suction is again drawn at the openings in the top face of said blade.

39. The apparatus in accordance with claim 38 wherein said blade has an insert of material with a high coefficient of friction in its top face for effective contact between said blade and said object.

40. The apparatus in accordance with claim 39 wherein said high coefficient of friction material is plastic and wherein at least one of said suction openings in said top surface of said blade passes through said insert.

41. The apparatus in accordance with claim 40 wherein said object is a packette containing a sample of a product and in which the downwardly projecting member of said gate is of yieldable material similar to the high coefficient of said friction material of said blade and a metal backup blade is positioned ahead of said yieldable member and spaced from the top surface of said blade so that once said blade moves forward it carries the bottom packette with it and the gate yields to allow passage of not more than a single packette therethrough.

42. The apparatus in accordance with claim 41 wherein the top surface of said shuttle blade is of concave configuration and said concaveness extends the length of said blade from the front to the back, a distance at least as long as the linear stroke of said blade.

43. The apparatus in accordance with claim 42 wherein said downwardly projecting member of said gate is convex in shape and is of such configuration that when it is centered above said blade and its lowest center portion is spaced from the lowest center portion of the blade by a distance just sufficient to allow the passage of a single object therethrough, all other portions of said gate will be at a greater distance from all other portions of said blade.

44. The apparatus in accordance with claim 43 including means separate from said lifter fingers for supporting the back edge of a stack of objects from below at a level higher than the front edge with respect to the top surface of said blade.

45. The apparatus in accordance with claim 43 wherein the positions in the reciprocating travel of said blade at which said lifter fingers lift and drop are both independently adjustable and the suction means to cause suction in the face of said blade is independently made and broken with regard to said travel of said blade and the lifting movement of said lifter fingers.

46. The apparatus in accordance with claim 45 wherein the bottom portion of said yieldable side guide is held in a fixed position from the rigid side guide by which it is supported.

47. The apparatus in accordance with claim 1 wherein said magazine includes hopper means for holding a supply of objects to be fed by removal of individual objects from the bottom of a stack of objects in said hopper including hopper side guides which in turn include rigid hopper side guides on either side of the hopper with a yieldable inner side guide member supported from the rigid side guide on at least one side and normally held in a fixed position parallel to both rigid side guides but yieldably movable only toward the rigid side guide by which it is supported whereby said magazine may be continuously loaded from the carton of objects having an open top being converted thereover with retaining means held until the supply of objects may be positioned in said hopper.

48. The apparatus in accordance with claim 47 wherein said independent means for supporting the back edge of said stack of objects is adjustable and there is a vertical slideable member with horizontal downwardly projecting ratchetlike teeth extending across its width along its lower portion and mounted on the inner face of said gate supporting member, such that the said downwardly projecting teeth contact the leading edges of objects in said stack and including means for vertically reciprocating said slideable member, the vertical reciprocation of said sliding member being timed such that the sliding member moves down when said lifter fingers move up.

UNITED STATES PATENT OFFICE
CERTIFICATE OF CORRECTIONPatent No. 3,630,513 Dated December 28, 1971Inventor(s) William W. Davidson, Jr. et al

It is certified that error appears in the above-identified patent and that said Letters Patent are hereby corrected as shown below:

In the Abstract, line 34, insert a period after "malfunctioning";
Column 30, line 27, for "related" read -- released --;
Column 43, line 28, for "on" read -- of --;
Column 43, line 75, between "speed" and "lugged" for "or" read -- of --;
Column 47, line 19, for "sample" read -- article --.

Signed and sealed this 18th day of July, 1972.
